UNITED STATES PATENT OFFICE.

EDMUND WATT HANCOCK, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed October 20, 1920. Serial No. 418,191.

To all whom it may concern:

Be it known that I, EDMUND WATT HANCOCK, a citizen of the United States, residing at New York, in the county of New York, State of New York, have invented certain new and useful Improvements in Telephone-Exchange Systems, of which the following is a full, clear, concise, and exact description.

This invention relates to telephone systems and particularly to systems in which machine switching mechanism is used for establishing connections between subscribers' lines.

In telephone exchange systems where a comparatively large number of offices are located in the same area, and the interoffice traffic is heavy, it is found convenient and economical to dispose of a portion of this traffic by routing calls to a central switching or tandem office, from whence they are then directed to any of the desired outlying offices. Connections are first extended by automatic switches under the control of a register sender, positioned either by subscribers' dials or operators' equipment, from the originating office over trunks leading to the tandem office. At the tandem office selective switches are operated, in accordance with that portion of the desired designation that identifies the outlying office containing the called line, to further extend the connection to the latter office. Here, dependent upon the type of the called office, the connection is completed automatically to the called line in accordance with the registered designation or is extended to an operator, who is advised of the identity of the wanted line by indicating mechanism automatically operated over the extended connection.

Due to the fact that the service requirements of many of the offices of the entire exchange system are peculiar to each of the particular offices and differ from those of the others, the equipment, designed for controlling the switches to establish local connections in a given office, is not suited to operate directly in the control of switches in distant offices for effecting interoffice connections. In other words, the register sender in a given office, upon which the called designations are registered, is adapted to control the switches for completing any type of a local call that is required, but on interoffice calls, the sender in the originating office is unsuited in some instances to control di-

rectly, the switches or other automatic apparatus with which the distant offices may be equipped. As an example of this condition, certain offices in the system may be provided with call indicators which operate on the revertive impulse principle while other offices are equipped with call indicators operated by code impulses.

In view of the large number of outlying offices to which the selective switches at the tandem point have access, and since many of these offices are designed to receive several classes of calls, it becomes necessary to provide at the tandem office, a register sender capable of recording a large number of class and office designations to enable the extension of all calls routed through the tandem office. To accomplish this, a controlling equipment is provided at the tandem office, including selective switches which are arranged to be selectively operated in accordance with the setting of registers, which registers are positioned by impulses representing the designation of called offices. These switches when positioned, causes the register sender to record the office designation to determine the selective extension of the connection to the outlying called office.

Furthermore, since, as above explained, the senders located in originating offices are unable to control all the switching mechanism involved in an interoffice call routed through the tandem point, it is necessary to transfer the designation first registered on the sender at the originating office to the register sender in the tandem office. With the registration thus transferred, the tandem office sender takes up a corresponding setting and controls the selective switches to extend the calling line to a distant called office where it is further extended to the wanted line therein.

An object of the invention is a system in which the designation of a line is recorded on a controlling mechanism, and then transferred to a second controlling mechanism which controls automatic switches of the panel type to establish a talking connection.

This invention has as another of its objects, the provision in a system of the above character, of a controlling mechanism wherein registers, which are positioned by impulses representing a desired designation, determine the variable operation of a selective switch, which in turn causes a corre-

sponding registration to be produced on the register sender to control the selective extension of a connection in accordance with the desired designation.

5 Another object of the invention is the provision of means whereby the registration of a designation on the sender in one office is automatically transferred to a second office to determine the variable operation of 10 a switch, which switch in its operated position causes the transferred registration to be reproduced on the register sender at the second office.

A feature of the invention relates to the 15 provision of a plurality of registers, which take up positions in accordance with designation impulses, and jointly determine the setting of a variably operable switch to cause the registration of the designation on 20 a switch controlling register sender.

A further feature relates to means whereby the settings of the impulse positioned registers serve to select one of a plurality of switches and jointly determine the operation 25 of the selected switch to cause the registration on the sender of a designation represented by the impulses which position said registers.

A still further feature of the invention relates to the provision of means for transferring the registration on a sender to a set of registers which then determine the operation, of a selective switch to reproduce the transferred registration on the switch 35 controlling registers of a second sender.

These and such other features as may be contemplated by the present invention will become more clearly understood from a consideration of the following description.

40 In the drawings, Figs. 1 to 16, when arranged in the order shown in Fig. 17, illustrate the circuits and apparatus of a telephone exchange system for handling inter-office traffic in accordance with the principles 45 of this invention.

Fig. 1 shows a calling subscriber's line terminating in a jack at an operator's position in the originating office, and also the circuits of a district selector switch.

50 Fig. 2 shows a sequence switch by means of which the operator's telephone set is automatically connected to and disconnected from the talking circuit in Fig. 1.

Fig. 3 shows a cord finder switch which 55 operates automatically to associate an allotted register sender with the particular cord circuit that the operator has chosen for use. This figure also illustrates an auxiliary switch for allotting an idle cord finder and register sender for use.

Fig. 4 illustrates the office keys on the operator's keyboard which determine the position of the corresponding registers in accordance with the designation of the called 60 office.

Fig. 5 shows the remaining or numerical keys on the operator's keyboard and the numerical and stations registers which take up settings under the control of said keys to record the numerical designation of the 70 called line in the desired office.

Fig. 6 illustrates a set of counting relays and a sender sequence switch for controlling the selective movements of the automatic switches in accordance with the designation 75 registered on the office and numerical registers.

In Fig. 7 is shown the incoming end of a trunk at a tandem office terminating in a district selector switch. In this figure, there 80 is also shown an auxiliary switch individual to the district selector for associating there-with an idle register sender in the tandem office.

Fig. 8 shows an office selector switch in 85 the tandem office, which has access to trunk lines leading to outlying offices.

Fig. 9 shows the incoming end of a trunk from the tandem office terminating in a first or incoming selector switch located in the 90 distant office.

Fig. 10 illustrates a final selector switch in the distant office, by means of which, connections are completed to the called subscribers' lines.

Fig. 11 illustrates a plurality of intermediate registers and the controlling circuits therefor, to which the office and numerical designations of a called line are transferred from the register sender in a distant 95 calling office.

Fig. 12 shows two selective switches, known as the translator switches, which are variably operable under the control of certain of the registers shown in Fig. 11. There 105 is also shown, diagrammatically, a machine for generating current impulses.

Fig. 13 illustrates a plurality of relay registers adapted to be positioned by impulses sent from the impulse machine as 110 determined by the setting taken by one of the translator switches.

Fig. 14 shows a class sequence switch and its associated circuits for making the necessary modifications in the operation of the 115 sender to take care of the different classes of calls required.

Fig. 15 illustrates the counting relay set and sequence switch of the tandem office sender for controlling the selector switches 120 in the tandem office and also the selective mechanism in the distant called office.

Fig. 16 shows a sequence switch and its associated circuits which controls the operations involved in the transfer of the 125 registration to the tandem office sender and which also cooperates with said sender in the extension of the connection to the called line.

The selective switches in Figs. 1, 7, 8, 9 130

and 10 are of the power driven panel type shown in the patent to Craft and Reynolds, No. 1,123,696, issued January 5, 1915. These switches are provided with five sets of 5 brushes, multiplied together and mounted on a common brush shaft. Each set of brushes has access to a section of the terminal bank containing one-hundred sets of terminals and is arranged to be tripped in the first 10 selecting movement of the switch so as to make contact with said terminals.

The cord finder 350 in Fig. 3, is also a power driven switch of the same general structure except that only one set of brushes 15 is provided and consequently no initial tripping operation is required. The translator switches 1250 and 1260 in Fig. 12 are likewise of the power driven type and differ from the switch shown in Fig. 1, only in 20 the details of operation and in the manner of connecting the brushes and terminals.

The sequence switches illustrated by the usual convention throughout the several figures of the drawing are of the same construction as the one described in the patent to Reynolds and Baldwin, No. 1,217,808, issued February 9, 1915. Where but one sequence switch magnet occurs in a figure of the drawing, all contacts appearing in the 30 same figure are controlled by such magnet. In Fig. 3, the allotter sequence switch magnet 310 controls only the contacts located within the broken rectangle at the right-hand side of the sheet; whereas the remaining contacts are controlled by the sequence switch magnet 300. In Figs. 4 and 5, the contacts located within the spaces bounded by the vertical broken lines are controlled by the magnets correspondingly situated. 35

40 In Fig. 7, the contacts located within the small dotted rectangle are governed by the sender selector sequence switch 710 and the remaining contacts in this figure are controlled by sequence switch magnet 700. In 45 Fig. 11, magnets 1110, 1120, 1130, 1140, 1150, 1160, 1170 and 1180, are located within the spaces bounded by the vertical broken lines and govern the sequence switch contacts appearing in the corresponding spaces. 50 Magnet 1100 in addition to governing the sequence switch contacts to the left of the left-hand broken line in Fig. 11, also controls all sequence switch contacts appearing in Fig. 12.

55 General description.

According to the system disclosed herein, interoffice calls originating in certain offices 60 of the exchange, such as the one illustrated in Figs. 1 to 6 inclusive, are first routed to a central switching or tandem office, as shown in Figs. 7 and 8 and Figs. 11 to 16 inclusive. Here, the district and office switches are operated in accordance with 65 the office designation of the desired line to

further extend the connection over an outgoing trunk leading to the distant called office. If the terminating office is arranged for full mechanical connections, such as the office illustrated in Figs. 9 and 10, the incoming and final selector switches are set up in accordance with the numerical designation of the wanted line to complete the establishment of the connection. By placing the interoffice traffic, or, at least a portion thereof, on the tandem switching basis, 70

it becomes obvious that the switches of the tandem office must be capable of selecting trunks leading to any outlying office in the exchange. The register sender, in addition 80 to controlling the district and office switches for making a large number of different office selections, must also be designed to differentiate between the various classes of calls. For example, some of the outlying offices to 85 which the connections are extended through the tandem point may be equipped with the selector switches for completing calls on the full mechanical basis, while other offices may be equipped with call indicators which 90 are controlled by the register sender in the tandem office to indicate to the operator the numerical and stations designation of the called line. Another class of calls may require the further extension of a connection 95 from the tandem office to a second tandem office from whence it is extended to the terminating office. To meet these operating conditions, the register sender in the tandem office must be designed for a large number 100 of class and office settings.

The register sender in the originating office is of the sequence switch type, arranged to control the sequence switches by means of reverting impulses. This sender 105 may also control the completion of connections to certain call indicator offices, provided the call indicators are arranged to work on the reverting impulse principle. In such a case it would not be necessary to 110 rout the call through the tandem office. In case, however, the call in the originating office is one for an office equipped with call indicators operating on the code impulse principle, or provided with any other mechanism which the sender in the originating office is unsuited to cooperate with, it then becomes necessary, as explained, for the connection to be extended through the tandem office. For the sake of clearness, the tandem office sender in the present disclosure 115 has been simplified by removing the circuits and apparatus which cause the transmission of code impulses to position the call indicator in the distant office, inasmuch as the description to be given herein will take account only of a full mechanical connection. From the foregoing it will be seen that the register sender at the tandem office besides being capable of taking a large number of 120 125 130

settings must also be arranged to assume these settings in response to means controlled from the distant calling office.

The originating office in the present instance, is shown to be of the semi-automatic type, with the subscribers' lines appearing in jacks at the operators' positions. So far as the invention is concerned, however, such office might equally as well be equipped with full automatic switching equipment. At the initiation of a call, the operator inserts the plug of an idle cord circuit in the jack of the calling line and receives from the calling subscriber, the name of the called office and the number of the wanted line therein. The insertion of the plug of the operator's cord circuit in the jack of the calling line initiates the automatic operation of an allotted cord finder 350, which finds the cord taken for use, and associates therewith an idle register sender.

The operator's keyboard is equipped with three rows of office keys, as seen in Fig. 4. By assigning three-digit numbers for the identification of the called office, these three rows of keys, when taken in their several possible combinations, permit the registration of a large number of office codes. Having received the wanted designation, the operator presses a key in each of the three rows of office keys, which cause the setting of the three corresponding registers 400, 410, and 420, to register the desired office designation. She also depresses a key in each of the rows of numerical keys, shown in Fig. 5, to record the number of the wanted line.

The district switch 150 is now operated in accordance with the settings of the office registers 400, 410, and 420 to select a trunk 155, 156, which terminates in the district switch 750 at the tandem point. The seizure of the trunk 155, 156 causes the operation of the sender selector sequence switch 710 for the purpose of associating an idle register sender with the district selector switch 750. As soon as an idle register sender has been found and associated with the district selector, the office registration recorded on each of the three registers 400, 410, and 420 is transferred over the trunk 155, 156 to the three corresponding intermediate registers 1100, 1110, and 1120. Following the transfer of the office record, the numerical registration is likewise transferred from the numerical registers at the originating office to corresponding registers 1130, 1140, 1150, 1160, 1170, and 1180. The office record having been transferred to the temporary registers 1100, 1110 and 1120, it now becomes necessary to reproduce this record on the relay registers, shown in Fig. 13, of the tandem office sender to enable the required control of the selective switching

mechanism to further extend and complete the desired connection.

The tandem office sender disclosed in the present system has a capacity for the selection of 400 different outlying offices. For adjusting the relay registers and sender to any one of the 400 different combinations two translator switches 1250 and 1260 are provided. Each translator switch is equipped with five sets of brushes, only one of the same being shown in the drawings. Each brush set has access to a section of the terminal bank containing forty sets of terminals. Each section of forty terminals is divided into two groups of twenty each, while each group of twenty is further subdivided into groups of ten sets each. The brushes of each translator are multiplied together and also multiplied to the brushes of the other translator switch, as illustrated in the drawing. As will be more clearly brought out in the detailed description following, the three registers 1100, 1110, and 1120 jointly determine the selection of one of the translator switches, the tripping of the proper set of brushes, the selection of the necessary groups of twenty and ten and the selection of the required set of terminals therein.

The impulse machine, diagrammatically illustrated at 1270, consists in practice of a cylindrical drum containing circular rows of metallic segments variously arranged about the circumference of the drum. Each row may comprise from one to four segments and is so arranged with respect to other rows as to give a large total number of variations. The metallic segments are spaced apart but are electrically connected together and to a source of battery. In the drawing, where the development of the cylindrical drum is given, battery current is shown to be supplied over the brush 1244 to the continuous metallic segment 1249, which is understood to be electrically connected to all metallic segments on the drum. A brush such as 1238, 1239, etc., is arranged to engage the metallic segments of each circular row in the rotation of the impulse machine.

The sets of the terminals in the banks of the translator switches are wired to the brushes of the impulse machine. Since, as shown, each set of terminals in the translator bank consists of five terminals, it is possible to obtain a given combination for every set of terminals of the entire 400 sets by wiring each of these sets to a different group of five brushes at the impulse machine. When, therefore, one of the two translator switches has been selected and positioned on a set of terminals corresponding to the joint settings of the intermediate registers 1100, 1110, and 1120, a code of impulses is transmitted from the impulse ma-

chine to set the class sequence switch 1400 and the office registers in Fig. 13 in accordance with the class of the call being made and the code of the office in which the called 5 line appears.

The tandem office sender now functions to control the district and office switches to extend the connection to the outlying terminating office and then to control the incoming and final switches therein to complete the connection to the called line.

Having thus given a general description of the system and the manner in which the same operates, a detailed description will 15 now be made of the establishment of a connection from the calling subscriber's line 101 in the originating office to a called subscriber's line, such as line 1060, in the terminating office.

20 Initiation of the call and operation of the cord finder switch.

Upon the removal of the calling subscriber's receiver from the switchhook, a circuit is closed over the contacts of relay 106 for the line relay 102. Relay 102 attracts its armature and closes a circuit for the line lamp 103. The operator, observing the illumination of the lamp 103, seizes the plug 30 105 of an idle cord circuit and inserts it in jack 104. The insertion of the plug in the jack closes a circuit from battery through the winding of cutoff relay 106, sleeve of jack 104, sleeve of plug 105, winding of relay 107 to ground. Relay 107 becomes energized and completes a circuit from ground through its armature and front contact, conductor 157, upper left-hand contact 212 (1) of sequence switch 200, winding of sequence 35 switch magnet 200 to battery and ground. The sequence switch 200 becomes energized in this circuit and advances from position 1 into position 7. In position 7 of the sequence switch 200, the calling subscriber's line and the operator's telephone set are connected in talking relation to each other over contacts 201 and 202, and talking current is supplied through the left-hand windings of repeating coil 112 and contacts 203 40 and 204.

With the listening sequence switch 200 in position 7, a circuit is established from battery through the winding of sequence switch magnet 100, conductor 158, contact 206 45 (2+7), upper right-hand contact 139 (1) to ground. The district selector sequence switch 100 advances from position 1 into position 2. In position 2 of sequence switch 100 a circuit is closed from battery through contact 151 (2+18), calling supervisory lamp 114, resistance 159 to ground. Since the calling subscriber's receiver is off the switchhook, and relay 113 is energized, the lamp 114 does not illuminate due to the 50 shunt circuit as follows: battery, lower con-

tact 151 (2+18), upper contact 151 (14+12), armature and contact of relay 113, resistances 160 and 159 to ground. Sequence switch 100 in position 2 closes a circuit from ground through the interrupter 122, lower 70 right-hand contact 149 (2+11), upper right-hand contact 149 (2+12), lamp 121, resistance 161 to battery and ground. Due to the action of interrupter 122, the lamp 121 is intermittently illuminated and is maintained illuminated until the sequence switch 100 leaves position 11 to indicate that during this period a register sender is associated with the cord circuit.

The district sequence switch 100, on reaching position 2, also initiates the operation of the allotted cord finder switch 350. Before proceeding further, however, a description will be given of the function of the allotter switch 310 in assigning for use the cord 80 finder switches 350 and their associated senders. As shown, the allotter switch 310 is designed to control the allotment of three cord finder and register sender units, the allotting positions of this switch being 1, 90 6 and 12. It will be assumed that the cord finder unit, shown in the drawing, which is allotted in position 1 of switch 310 has been taken for use on a previous call and the sequence switch 300 thereof has just been 95 advanced into position 18 in a manner to be fully described hereinafter. At the time the sequence switch 300 reached position 8 in the previous use of the cord finder 350, a circuit was closed from battery through the 100 winding of sequence switch magnet 310, upper contacts 331 (8+17), lower right-hand contact 342 (1) to ground. In this circuit the allotter sequence switch 310 was driven from position 1 into position 2. 105 When sequence switch 300 reached position 18 another circuit was closed from battery through the magnet of sequence switch 310, upper contact 344 (2), right-hand contact 329 (18) to ground, driving sequence switch 110 310 out of position 2 and into position 6, the second allotting position. If the second cord finder (not shown) were busy at this time the sequence switch 300 of such finder is in some position between 8 and 17 and 115 a circuit is therefore established from battery through the winding of sequence switch magnet 310, the upper contacts 331 of the second cord finder sequence switch 300, thence over the conductor 380, lower left-hand contact 342 (6) to ground. The allotter sequence switch therefore passes out of position 6 and into position 7. Since the sequence switch 300 of the cord finder 350, shown, is assumed to be standing in 120 position 18, sequence switch 310 is immediately driven from position 7 into position 12 by means of the circuit traced including contacts 344 and 329. Should the third cord 125 finder and register sender unit be busy at 130

18
this time, the corresponding sequence switch 300 is standing in some position between 8 and 17 and the allotter sequence switch 310, is moved out of position 12 by means of the 5 circuit over the corresponding contacts 331, conductor 354, and the upper right-hand contact 342 (12). In position 13 the above traced circuit, through contacts 344 and 329, is closed to move the sequence switch 310 10 into position 1, which is the allotting position for the cord finder shown. The cord finder sequence switch 300 is now advanced from position 18 into position 1 in a circuit from battery through the winding of 15 sequence switch magnet 300, upper right-hand contacts 337 (18), lower right-hand contact 342 (1) to ground.

With the district sequence switch 100 in position 2 and the cord finder sequence 20 switch 300 in position 1, a circuit is closed from ground through the upper left-hand contact 139 (2), upper right-hand contact 205 (7), upper right-hand contact 330 (1+1½), lower left-hand contact 330 (1+2), 25 winding of relay 301 to battery and ground. Relay 301 becomes energized and closes a circuit from ground through its right-hand armature and front contact, lower right-hand contact 335 (1), winding of sequence 30 switch magnet 300 to battery and ground, driving sequence switch 300 into position 2. In position 2 relay 301 remains energized in a circuit from battery through its winding, the left-hand contacts 330, back contact and 35 right-hand armature of relay 302 to ground. In position 2 of sequence switch 300, a circuit is closed as follows for the updrive power magnet 305, to drive the brushes of the cord finder switch over the terminal 40 bank in search of the set of terminals individual to the particular cord circuit taken for use by the operator; battery, through the winding of power magnet 305, lower left-hand and upper right-hand contacts 323 45 (2), front contact and right-hand armature of relay 301 to ground. When the hunting brush 307 engages the terminal 314 identifying the desired cord circuit, a circuit is established from battery through the winding of 50 relay 302, upper left-hand contact 334 (2), brush 307, terminal 314, conductor 355, upper left-hand contact 205 (7), upper left-hand contact 139 (2) to ground. Relay 302 is energized and opens the above traced 55 circuit for relay 301. Relay 301, however, remains energized in a holding circuit closed through its contact and left-hand armature, commutator 321, and brush 320 to ground. When the brushes are accurately centered 60 upon the terminal set the brush 320 engages an insulating segment of commutator 321 and the holding circuit of relay 301 is opened permitting this relay to deenergize. Relay 301 opens the circuit of the updrive 65 power magnet 305, causing the brush shaft

to come to rest. Relay 302 closes a holding circuit for itself from battery through the winding of said relay, upper right-hand contact 334 (2+16), contact and left-hand armature of relay 302, brush 309, terminal 70 316, conductor 356, lower left-hand contact 145 (2+11), upper left-hand contact 145 (2+16½), back contact and left-hand armature of relay 118 to ground. Relay 301, on deenergizing, also completes a circuit from ground through its righthand armature and back contact, lower left-hand contact 335 (2), winding of sequence switch magnet 300 to battery and ground, driving the said sequence switch out of position 2 and into position 3. 75

Registration of the desired designation.

The operator's telephone equipment (not shown) having been automatically connected 80 to the calling line, she converses with the calling subscriber and obtains from him the name of the called office and the number of the desired line therein. It will be assumed that the called office is identified by the three 85 digit code 3 5 3 and that the number of the desired line therein is 4 7 5 2. As will be brought out later, this particular office belongs to the second group of 200 offices to which the district and office switches at the 90 tandem point have access. The transfer of the registered code 3 5 3 to the relay registers of the tandem office sender for the purpose of selecting this office is therefore governed by the translator switch 1260. The 95 operator next proceeds to depress No. 3 key 406 in the first row of office keys, No. 5 key 414 in the second row, and No. 3 key 424 in the third row. She also sets up the numerical designation on her keyboard by depressing 100 No. 4 thousands key 501, No. 7 hundreds key 511, No. 5 tens key 521, No. 2 units key 531, and the start key 541. These keys are all of the locking type and are released by means of the key control magnets 105 430, 431, 432, 433, and 434. Contacts 407, 415 and 425 are common row contacts which close whenever a key in the corresponding row is depressed. Contacts 553, 554, 555, and 556 are also common to their respective 110 rows of keys but are opened instead of being closed whenever a key in the corresponding row is operated. The depression of these keys completes circuits for the corresponding registers 400, 410, 420, 500, 510, 520, 530, and 540, which rotate from the positions in which they happen to be standing to take up positions in accordance with the depressed keys. The circuits for the registers 115 400, 410 and 420 may be traced from ground through the closed contacts 407, 415, and 425, conductor 440, right-hand armature and contact of relay 402, winding of magnet 400, conductor 441, upper left-hand contact 347 to battery and ground. Another branch of 120 125 130

this circuit leads from conductor 440, through the armature and back contact of relay 411, winding of register magnet 410, conductor 442, upper right-hand contact 347 to battery and ground. The third branch leads from the conductor 440, through the armature and back contact of relay 421, winding of register magnet 420, conductor 448, lower right-hand contact 347 to battery and ground. When the start key 541 has been depressed, a circuit is closed from ground through the outermost left-hand contact of said key, conductor 557, the winding of relay 551, the lower left-hand contact 351, conductor 357, winding of relay 304, upper contact 341 (1), upper left-hand contact 340 (1), upper left-hand contact 349 to battery and ground. Relays 304 and 551 become energized in this circuit. Relay 551 closes a substitute circuit for itself from ground through the lower contact 331 (1+6), conductor 612, left-hand armature and front contact and winding of relay 551 to battery over the circuit above traced. At its right-hand armature and contact, relay 551, closes an energizing circuit for relay 550. Relay 550 completes a circuit from ground through its left-hand armature and contact to conductor 558, thence through the right-hand armature and contact of relay 503, winding of register magnet 500, conductor 559, upper right-hand contact 348 to battery and ground. A branch of this circuit leads to the right-hand armature and contact of relay 513, winding of register magnet 510, conductor 560, lower right-hand contact 348 to battery and ground. Another branch of the circuit leads through the right-hand armature and back contact of relay 523, winding of register magnet 520, conductor 561, lower left-hand contact 348 to battery and ground. Another branch leads to the right-hand armature and contact of relay 533, winding of register magnet 530, conductor 562, upper right-hand contact 349 to battery and ground. The last branch of the circuit may be traced from conductor 558 through the armature and back contact of relay 543, winding of register magnet 540, conductor 563, lower right-hand contact 349 to battery and ground. In the circuits above traced the office and numeral registers are operated to assume positions corresponding to the actuated keys.

When the register 400 reaches position 3, a circuit is closed from ground through the contact of the depressed key 406, upper left-hand contact 401 (3), winding of stop relay 402, lower right-hand contact 353, winding of relay 304, upper contact 341 (1), upper contact 340 (1), upper left-hand contact 349 (2+6), to battery and ground. Relay 402 becomes energized and opens the operating circuit of register 400 permitting the latter to stop in position 3. When register 410 reaches position 5, a circuit is closed from ground through the contacts of key 414, upper right-hand contact 412 (5), winding of stop relay 411, lower left-hand contact 353, (1), and thence to battery as described. When register 420 reaches position 3 a circuit is established from ground through the contacts of key 424, lower left-hand contact of key 422 (3), winding of relay 421, lower right-hand contact 352 (1), and thence to battery. Relays 411 and 421 open the circuits of registers 410 and 420, causing them to cease rotation. When registers 500, 510, 520 and 530 reach positions 4, 7, 5, and 2, respectively, similar circuits are closed for their stop relays 503, 513, 523, and 533, and these registers come to rest in the proper positions. The stations register 540, on reaching position 5, completes a circuit from ground through the right-hand contact of key 552, conductor 564, inner left-hand contact of start key 541, upper right-hand contact 542 (5), winding of stop relay 543, and thence to battery at contact 345. Relay 543 opens the circuit of register 540, causing the latter to stop in position 5. The register 540, which takes up a setting in response to the operation of the start key, may also be positioned by means of stations key where it is necessary to control the selection of ringing current on party lines. These stations keys are not shown in the present disclosure since the application of ringing current to party lines in the office of the type to which the present call is being extended does not require the transmission of additional impulses.

As will be seen hereinafter, the sender sequence switch 600 depends upon the setting of all numerical registers for its advancement. Where the called line is a party line and stations keys are used, the stations register 540 is set by these keys and the sender sequence switch advances after all the numerical registers and the stations register 540 have been positioned. For uniformity in operation, register 540 is arranged, as shown in the drawing, to take a setting on calls not involving party lines in response to the start key 541.

As soon as the first two office registers 400 and 410 have taken up their settings and relays 402 and 411 are operated, a circuit is closed from ground through the row contacts 407, 415 and 425, conductor 440, armature and front contact of relay 411, left-hand armature and contact of relay 402, conductor 444, lower righthand contact 337 (3), winding of sequence switch magnet 300 to battery and ground. Sequence switch 300 advances from position 3 into position 4.

Operation of district switch.

With the cord finder sequence switch 300 in position 4 a circuit is established for the

sender sequence switch 600 from battery through the winding of said sequence switch, upper right-hand contact 603 (1), lower left-hand contact 326 (4+6) to ground. Sequence switch 600 leaves position 1 and moves into position 2. In this position the fundamental circuit is closed for controlling the brush selecting operation of the district switch 150. The fundamental circuit 5 may be traced from battery through the winding of relay 116, lower left-hand contact 152 (2), lower right-hand contact 152 (2+5), conductor 162, terminal 319, brush 313, conductor 358, contact and outer left-hand armature of the O' counting relay 613, winding of the stepping relay 601, lower contact 607 (2), conductor 359, resistance 360, upper right-hand contact 326 (3+8) to ground. Relay 116 becomes energized and 10 completes a circuit from battery through the winding of sequence switch magnet 100, lower left-hand contact 147 (2), front contact and left-hand armature of relay 116, back contact and right-hand armature of 15 relay 118 to ground. Sequence switch 100 moves from position 2 into position 3 and relay 116 is maintained energized over a locking circuit traceable from battery through the winding and contact and right-hand 20 armature of said relay, lower right-hand contact 153 (2+5), lower right-hand contact 152 (2+5), and thence to ground as described. With sequence switch 100 in position 3, a circuit is completed as follows for the upper 25 drive power magnet 123 to elevate the brush shaft in the brush selecting movement of the switch: battery, through the winding of said magnet, lower right-hand contact 147 (3), front contact and left-hand armature of 30 relay 116 to ground over the back contact and right-hand armature of relay 118. The stepping relay 601, which also energizes in the fundamental circuit, closes a circuit from ground through its armature and contact, conductor 614, upper contact 346 (3+8), upper right-hand contact 608 (2), conductor 565, upper left-hand contact 403 (3), of register 400, conductor 445, armature, and back contact of No. 1' counting relay 615, winding 35 of No. 1 counting relay 616 to battery and ground. Relay 616 becomes energized and closes a circuit from battery through its winding and the winding of relay 615 in series, contact and armature of relay 616, upper contact 617 (2), to ground. Relay 615, however, does not energize at this time since it is shunted out by the direct path to ground closed at the armature and contact of relay 601. As the brush shaft of the 40 district selector switch approaches its first brush tripping position, brush 129 engages the metallic segment of the commutator 126 and a circuit is closed as follows in shunt of the winding of stepping relay 601, bat- 45 teries, through the winding and contact and right-hand armature of relay 116, lower right-hand contact 153 (2+5), upper right-hand contact 152 (2+3), commutator 126, brush 129, lower right-hand contact 139 (8+6) to ground. Relay 601, being shunted, releases its armature and removes the short circuit around the winding of relay 615. Relay 615, therefore, energizes and locks up in series with relay 616 in the circuit above traced. As brush 129 engages the next insulating segment, relay 601, becomes energized and the stepping circuit is now extended by way of conductor 445, armature and front contact of relay 615, and winding of the O' counting relay 618 to battery and ground. In a similar manner relay 618 prepares a series circuit for the O' relay 613, but this latter relay does not energize due to the short-circuit maintained by the stepping relay 601. As the brush shaft of the district switch approaches the next brush tripping position, the stepping relay 601 is again shunted and releasing its armature permits the relay 613 to energize and lock up in series with relay 618. The O' relay 613, at its inner armature and contact, closes a circuit including the left-hand contact 617 (2) for driving the sender sequence switch 600 in position 3. Relay 613, at its outer armature, also opens the fundamental circuit. As the sender sequence switch leaves position 2, the right-hand contact 617 is opened to permit the release of the energized counting relays. 50 As soon following the opening of the fundamental circuit by the O' counting relay as the brush 129 engages the next insulating segment of commutator 126, relay 116 becomes deenergized to open the circuit of the updrive power magnet 123, whereby the brush shaft ceases its upward movement. Relay 116 also completes a circuit from battery through the winding of sequence switch magnet 100, lower right-hand contact 140 (3) back contact and left-hand armature of relay 116, back contact and right-hand armature of relay 118 to ground. Sequence switch 100 advances from position 3 into position 4. In position 4 a circuit is closed from battery through the winding of the trip magnet 125, upper left-hand contact 142 (4) to ground. The trip magnet 125 energizes and rotates the trip spindle so that on the next upward movement of the brush shaft the selected set of brushes are tripped into operative relation with the corresponding section of the terminal bank. 55 If at this time the third office register 420 has found a position corresponding to the depressed key, a circuit is completed from ground through the row contacts 407, 415, and 425, conductor 440, armature and front contact of relay 421, conductor 446, lower 60

- left-hand contact 337 (4), winding of sequence switch magnet 300 to battery and ground. Sequence switch 300 advances into position 5 where a circuit is closed from battery through the winding of the sender sequence switch 600, lower left-hand contact 602 (2+18), upper left-hand contact 602 (3), left-hand contact 329 (5+15) to ground. Sequence switch 600 advances into position 5.
- 10 4. The cord finder sequence switch 300 immediately advances into position 6 by means of a circuit including the lower right-hand contact 336 (5). The fundamental circuit is again closed for controlling the group 15 selecting operation of the district switch. This circuit may be traced as follows: battery, through the winding of relay 116, lower left-hand contact 152 (4), lower right-hand contact 152 (2+5), thence over conductor 162, through the winding of stepping relay 601, lower contact 607 (4) to ground at contact 326. Relay 116 becomes energized and locks up in the manner above described and closes a circuit from battery through 20 the winding of the sequence switch magnet 100, lower left-hand contact 147 (4), front contact and left-hand armature of relay 116 to ground at the back contact and right-hand armature of relay 118. Sequence 25 switch 100 moves from position 4 into position 5 where the above traced circuit is again closed for the updrive power magnet 123. This magnet causes the elevation of the brush shaft, tripping the selected set of 30 brushes 133, 134, and 135, and advancing them over the terminals of the corresponding section in the group selecting movement.
- The stepping relay 601, which also becomes energized in the fundamental circuit, 35 closes a circuit from ground through its armature and contact conductor 614, upper contact 346, lower right-hand contact 608 (4), conductor 566, upper left-hand contact 404 (3), conductor 445, armature and back contact of relay 615, winding of relay 616 to battery and ground. Relay 616 becomes energized and closes the locking circuit for itself and relay 615, but the latter relay remains deenergized at this time. As the 45 brushes 133, 134, and 135 approach the successive groups of terminals, the commutator brush 130 engages the metallic segment of the group selecting commutator 127 to close the following circuit for shunting the stepping relay 601: battery, through the winding and contact and right-hand armature of relay 116, lower right-hand contact 153 (2+5), upper left-hand contact 152 (4+5), commutator 127 to the grounded brush 130.
- 50 60 For each deenergization of the stepping relay 601 a pair of counting relays is locked up. When the O' counting relay 613 becomes energized, it opens the fundamental circuit at its outer armature and closes a circuit at its inner armature including the left-hand contact 617 (4), for advancing the sender sequence switch 600 out of position 4 and into position 5.
- As soon after the fundamental circuit is opened by the O' counting relay as the 70 brush 130 energizes the next insulating segment of commutator 127, the circuit of relay 116 is opened and this relay deenergizes. Relay 116 opens the circuit of the updrive power magnet 123 to arrest the brushes 133, 75 134 and 135 in operative relation to the selected group of terminals. Relay 116 also completes a circuit from battery through the winding of sequence switch magnet 100, lower right-hand contact 140 (5), back contact and left-hand armature of relay 116 and back contact and right-hand armature of relay 118 to ground, driving said sequence switch out of position 5 and into position 6.
- In position 6 of the sequence switch 100, 80 relay 117 is energized by means of a circuit from battery through the right-hand winding of said relay, lower contacts 146 to ground. Relay 117 completes a circuit from battery through the winding of sequence 85 switch magnet 100, lower left-hand contact 147 (6), front contact and right-hand armature of relay 117, back contact and right-hand armature of relay 118 to ground. Sequence switch 100 advances from position 6 90 into position 7. Provided the first trunk, upon the terminals of which the brushes 133, 134, and 135 are now resting, is busy, relay 117 remains energized in a circuit from battery through the left-hand winding, front 95 contact and left-hand armature of said relay, brush 135 to the grounded test terminal 138. A circuit is therefore closed from battery through the winding of the updrive power magnet 123, lower right-hand contact 100 147 (7), front contact and right-hand armature of relay 117 to ground at the back contact and right-hand armature of relay 118. Magnet 123 causes the brush shaft to be moved upwardly in the trunk hunting movement. When the first idle trunk is found the circuit just traced for relay 117 is opened 105 since no ground potential exists on the test terminal 138. A momentary holding circuit is maintained as follows for the relay 117: 110 battery, through the right-hand winding of said relay right-hand contacts 146, centering commutator 128, brush 131, upper left-hand contact 147 (7), front contact and right-hand armature of relay 117 to ground at the 115 back contact and right-hand armature of relay 118. When the brushes are accurately centered on the terminals of the idle trunk, brush 131 engages an insulating segment of commutator 128, the holding circuit of relay 120 117 is opened and this relay releases its armatures to open the circuit of the power magnet 123. Relay 117 also completes a circuit at its outer armature and closes a circuit at its inner armature including the left-hand contact 617 (4), for advancing the sender sequence switch 600 out of position 4 and into position 5.

cuit from battery through the winding of sequence switch magnet 100, lower right-hand contact 143, back contact and right-hand armature of relay 117, back contact 5 and right-hand armature of relay 118 to ground to drive such sequence switch into position 8.

With sequence switch 100 in position 8 a circuit is established from battery through 10 the winding of the sender sequence switch 600, upper left-hand contact 603 (5), conductor 361, upper contact 325 (6+8), brush 311, terminal 317, conductor 367, lower left-hand contact 142 to ground. Sequence 15 switch 600 moves from position 5 to position 6. When sequence switch 600 reached position 5, a circuit was closed as follows for the O and O' counting relays: battery, through the windings of these relays, conductor 363, lower contacts 327 (4+8), lower contact 619 (5+8) to ground. On reaching position 6 therefore the sequence switch 600 is immediately driven into position 8 by means of a circuit from battery through the 20 winding of said sequence switch, contact and inner armature of relay 613, left-hand contact 617 (6) to ground. In position 8 relay 613 remains energized and the same circuit is again closed for driving the sequence switch 600 into position 9. While sequence switch 600 is passing from position 25 6 to position 8, a circuit is completed from ground over contact 620, conductor 365, left-hand contact 324 (5+8), brush 312, terminal 318, conductor 366, lower left-hand contact 153 (8), lower left-hand contact 152 (8), winding of relay 116 to battery and ground. Relay 116 becomes energized and closes a circuit from battery through the 30 winding of sequence switch magnet 100, lower left-hand contact 147 (8), front contact and left-hand armature of relay 116, back contact and right-hand armature of relay 118 to ground. Sequence switch 100 35 leaves position 8 and advances into position 9. In position 8 $\frac{3}{4}$ a holding circuit for relay 116 is established from battery through the winding, contact and right-hand armature of said relay, upper right-hand contact 154 (8 $\frac{3}{4}$ +9), upper left-hand contact 154 (8+11), conductor 366, and thence to ground as explained. As soon, however, as the sender sequence switch leaves position 8 and opens its contact 620, this holding circuit is severed and relay 116 becomes deenergized. Relay 116 now completes a circuit from battery through the winding of sequence switch magnet 100, lower right-hand contact 140 (9+10), back contact and left- 40 hand armature of relay 116 to ground at the back contact and right-hand armature of relay 118. The sequence switch 100 is therefore driven from position 9 over position 10 and into position 11.

Restoration of operators' keys.

65

If at the time the cord finder sequence switch 300 reaches position 6 the numerical and stations registers have all been positioned, or as soon thereafter as these registers have taken their settings, a circuit is established from battery through the winding of sequence switch magnet 300, lower left-hand contact 336 (6), conductor 569 over the armatures and contacts of relays 503, 513, 523, 533, and 543 in series, conductor 558 to ground at the contact and left-hand armature of relay 550. Sequence switch 300, therefore, advances from position 6 into position 7. In this position circuits are closed from battery through the contacts 338 and conductors 367, 368, 369, and 370 to the windings of magnets 430, 431, 432, 433, and 434. These magnets become energized and operate in the well known manner to release the depressed keys on the operator's keyboard. At the time the relay 304 was first energized and one or more of the registers has taken their set positions, a circuit was completed from battery through the contact and left-hand armature of relay 304, upper contact 341 (1), winding of relay 304, and thence by way of contacts 353, 352, and 351 over parallel paths through the windings of the stop relays 402, 411, etc., to ground at the contacts of the depressed keys in the several rows. The relay 304 by means of this parallel circuit, remains energized as long as there is a depressed key in any row of keys on the operator's board. When the last depressed key is released in position 7 of the cord finder sequence switch 300, relay 304 releases its armatures and completes a circuit from ground through the right-hand armature and contact of said relay, upper left-hand contact 337 (7), winding of sequence switch magnet 300, to battery and ground. Sequence switch 300 moves out of position 7 and into position 8, where as hereinbefore explained, a circuit is completed over contacts 331 for driving the allotter sequence switch 310 into position 2, preparatory to the assignment of another cord finder register sender unit.

Transfer of office and numerical registration.

In position 8 of the sequence switch 300, a circuit is established from battery through the winding of the sender sequence switch 600, left-hand contact 604 (9), left-hand contacts 328 (8), conductor 371, thence to conductor 447 (Fig. 4), lower left-hand contact 408 (3) to ground. Sequence switch 600 is energized in this circuit and moves from position 9 to position 10. Contact 408 and the two contacts shown immediately

120

125

above are governed by the register sequence switch 400, which serves also as a class sequence switch to control the operation of the sender in the originating office to take care of the different classes of calls that may be required. The conductors, such as conductor 447, leading to the closed position of these contacts, are shown terminating in circles containing Roman numerals. These 10 are in fact the same conductors represented by the circles in Figs. 3 and 6 containing the corresponding characters and have been shown in this manner to avoid unnecessary confusion of the drawing. In position 10 of 15 the sender sequence switch 600 the following circuit is established: battery, through the winding of relay 702 at the district switch in the tandem office, left-hand contact 728 (1+3), conductor 155, terminal 136, brush 133, upper right-hand contact 153 (11+16), lower right-hand contact 152 (9+11), conductor 162, terminal 319, brush 313, conductor 358, contact and outer armature of relay 613, winding of relay 601, upper contact 607 (10), conductor 372, brush 312, terminal 318, conductor 366, upper left-hand contact 154 (8+11), lower right-hand contact 154 (11+16), brush 134, terminal 137, conductor 156, upper contact 737 (1+3), 20 upper left-hand contact 739 (1+16), to ground. Relay 702 becomes energized and closes a circuit from ground through its right-hand armature and front contact, upper left-hand contact 734 (1+7), upper right-hand contact 734 (1+14), right-hand winding of relay 701 to battery and ground. Relay 701 attracts its armatures and closes a circuit from battery through the winding of sequence switch 25 magnet 700, lower left-hand contact 743 (1), front contact and left-hand armature 701, left-hand contacts 739 to ground, driving sequence switch 700 out of position 1 and into position 2. 30 Provided the sender selector sequence switch 710 is standing in a position corresponding to a busy register sender, relay 701 is maintained energized in position 2 of sequence switch 700 by means of a circuit 35 from battery through the left-hand winding of said relay, upper right-hand contact 735 (1+2), front contact and outer right-hand armature of relay 701, upper contact 741 (1+2), front contact and outer right-hand armature of relay 701, upper contact 741 (1+3), thence over one or another of the multiple contacts 758, 759, 753, or 760, depending upon the position in which the sender selector 710 is standing, to the lower 40 right-hand contact 738, (3+15) of the district switch that is maintaining the sender busy, upper left-hand contact 739 (1+16) at such switch to ground. Relay 701, by remaining energized, provides a circuit from 45 battery through the winding of sequence switch magnet 710, upper contact 742 (2), front contact and left-hand armature of relay 701, left-hand contacts 739 to ground. Sequence switch 710 commences to rotate to search for an idle register sender. As 50 the sequence switch 710 passes through its quarter positions a momentary circuit is established from ground through contact 761, upper right-hand contact 746 (2), lower contact 744 (2+13), inner right-hand armature and contact and right-hand winding of relay 701 to battery and ground. This momentary circuit is provided to prevent relay 701 from releasing and arresting the movement of sequence switch 710, provided 55 a register sender becomes idle at the instant when said sequence switch has just passed the position corresponding to such sender. In other words, the momentary circuit provided at contact 761 insures that the sequence switch 710 will continue to rotate until it reaches a position corresponding to a register sender which is at the time idle, thus preventing an incorrect positioning of the sender selector sequence switch. It will be 60 assumed that the register sender shown in the drawing is the first idle one to be encountered and that this sender is represented by position 1 of the sender selector 710. When, 65 therefore, the sender selector reaches position 1, the circuit of relay 701 is opened and this relay releases its armatures to open the driving circuit of said sender selector. Relay 701, moreover, completes a circuit 70 from battery through the winding of sequence switch magnet 700, lower right-hand contact 743 (2), back contact and left-hand armature of relay 701 to ground through the left-hand contacts 739. Sequence switch 700 moves in position 3. From positions 3 to 75 15 the selected sender is rendered busy by means of a circuit from ground through the upper left-hand contact 739 (1+16), lower right-hand contact 738 (3+15), thence in multiple to the lower right-hand contact 753 (14+14) of all other sender selectors similar to 710. 80 Relay 1602 of the control circuit shown in Fig. 16 is now energized in a circuit from battery through the winding of said relay, upper contact 1621 (1+2), conductor 762, lower left-hand contact 753 (18+2), lower right-hand contact 753 (14+14), and thence to ground at contact 739 as described. Relay 1602 at its outer right-hand armature 85 closes an operating circuit for relay 1603. Relay 1602 at its inner right-hand armature completes a circuit as follows for the energization of relay 1606 battery, through the winding of relay 1606, lower right-hand contact 1622 (1+11), upper right-hand contact 1624 (1+2), inner right-hand armature and contact of relay 1602, conductor 90 95 100 105 110 115 120 125

763, lower right-hand contact 748 of sequence switch 710, lower right-hand contact 734 (3+7), upper left-hand contact 734 (1+7), front contact and right-hand armature of relay 702 to ground. Relay 1606, on energizing closes a circuit as follows for advancing the district sequence switch 700 out of position 3 and into position 4: battery, through the winding of sequence switch 10 magnet 700, upper left-hand contact 732 (3), conductor 764, lower right-hand contact 747, conductor 765, inner right-hand armature and contact of relay 1603, upper right-hand contact 1630 (1), lower left-hand contact 1630 (1+10), front contact and right-hand armature of relay 1606, upper right-hand contact 1616 (1+11), to ground. In position 4 of switch 700, a circuit is closed from battery through the right-hand winding of relay 701, lower left-hand contact 745 (4) upper right-hand contact 744 (4) to ground. Relay 701 attracts its armatures and completes a circuit from battery through the winding of sequence switch 700, lower 25 left-hand contact 743 (4), front contact and left-hand armature of relay 701 to ground at the left-hand contacts 739. Sequence switch 700 moves into position 5 from whence it is driven into position 6 by means 30 of a circuit including the lower right-hand contact 732, and from position 6 the sequence switch advances into position 7 over a circuit closed at contact 733. As soon as sequence switch 700 leaves position 3, the 35 original circuit of relay 702 is opened at contact 728, but this relay remains energized in a circuit from battery through the winding thereof, contact 729 (3+7), outer left-hand armature and contact of relay 702, lower contact 731 (3+7), upper contact 730 (3+13), thence over conductor 155, as previously traced, through the winding 40 of the stepping relay 601 in the originating office and returning by way of conductor 45 156, upper contacts 736, lower right-hand contact 749 (1), conductor 766, contact and outer left-hand armature of relay 1603, conductor 1635, lower contact 1618 (1+10), to ground. When sequence switch 700 reaches 50 position 4 a circuit is closed from battery through the winding of relay 1604, upper right-hand and lower left-hand contacts 1631 (1), outer right-hand armature and contact of relay 1603, conductor 767, lower right-hand contact 755, lower right-hand contact 737 (4+7), upper left-hand contact 739 (1+16) to ground. Relay 1604 attracts its armatures and completes a circuit from battery through the winding of sequence switch 55 60 magnet 1600, lower right-hand contact 1627 (1), front contact and outer left-hand armature of relay 1604 to ground, whereby said sequence switch moves from position 1 into position 2. In position 2 and from there on 65 to position 18, relay 1602 is maintained ener-

gized in a locking circuit through its front contact, left-hand armature and lower contact 1621. Relay 1604 also locks up in a circuit from battery through its winding and inner left-hand armature and contact to 70 ground at the contact and outer right-hand armature of relay 1602.

The fundamental circuit including relay 702 and the stepping relay 601 having been established and the sequence switch 1600 75 driven to position 2, the apparatus is now in condition for transferring the registration of the register 400 to the intermediate register 1100. An energizing circuit for moving the register 1100 may be traced from 80 battery through the winding of said register, upper right-hand contact 1105 (1+5), conductor 1136, upper left-hand contact 1613, lower right-hand contact 1615 (2+10), left-hand armature and contact of relay 85 1606, lower right-hand contact 1622 (1+11), upper right-hand contact 1624 (1+2), inner right-hand armature and contact of relay 1602, conductor 763, and thence to ground, as above traced, at the front contact and 90 right-hand armature of relay 702. The register 1100 becomes energized and commences to rotate from its normal position 1. At the time the fundamental circuit was first closed, stepping relay 601, at its armature 95 and contact closed a circuit leading from the conductor 614, upper contact 346 (3+8), upper left-hand contact 609 (10), conductor 567, lower right-hand contact 409, conductor 416, armature and back contact of relay 100 621, winding of relay 622 to battery and ground. Relay 622 operates and closes a series circuit for itself and relay 621 to ground at the right-hand contact 617. Relay 621, however, is shunted at the armature 105 and contact of relay 601 and remains de-energized.

When the register 1100 passes position 1 $\frac{1}{2}$, a momentary circuit is closed as follows for relay 702 in shunt of the stepping relay 601, battery, through the winding of relay 702, contact 729 (3+7), outer left hand armature and contact of relay 702, lower contact 731 (3+7), lower contact 730 (3+15), lower right-hand contact 754, conductor 768, contact and inner left-hand armature of relay 1603, upper right-hand contact 1625 (1+11), conductor 1137, lower contact 1113 of register 1110 closed in its normal position N, contact 1103 (1 $\frac{1}{2}$), conductor 1138, left-hand contacts 1630 (1+10), front contact and right-hand armature of relay 1606, upper right-hand contact 1616 (1+11) to ground. The stepping relay 601, being shunted, deenergizes and opens 110 the short-circuit around the winding of relay 621. Relay 621 therefore, energizes and locks up in series with relay 622. Upon the opening of contact 1103 as register 1100 leaves position 1 $\frac{1}{2}$, the stepping relay 601 120 125 130

is again energized and the stepping circuit is now closed by way of conductor 416, armature and front contact of relay 621, armature and back contact of relay 623, 5 winding of relay 624 to battery and ground. In a similar manner relays 623 and 624 are locked up in series with each other in response to the next closure of contact 1103 in position 2 $\frac{1}{2}$. Likewise for each following 10 closure of the contact 1103, a pair of counting relays are locked up until the register 1100 reaches position 4 $\frac{1}{2}$ and the O' counting relay 613 is opened. Relay 613, at its outer armature, opens the fundamental 15 circuit and at its inner armature closes a circuit for driving the sender sequence switch out of position 10 and into position 11. In position 11 a circuit is closed from battery through the winding of sequence 20 switch magnet 600, left-hand contact 604 (11), left-hand contacts 328 (8), conductor 371, thence to conductor 447, Fig. 4, contact 408 to ground for driving sequence switch 600 out of position 11 and into position 12. 25 As soon after the opening of the fundamental circuit at the contact of the O' counting relay as contact 1103 of register 1100 moves out of position 4 $\frac{1}{2}$, the relay 702 de-energizes. Relay 702, on deenergizing, 30 opens at its right-hand armature, the above traced circuit for relay 1606 and also the operative circuit for the registers 1100. Register 1100 thereupon comes to rest in position 5 and the relay 1606 deenergizes. 35 Relay 1606, on releasing its armatures, completes a circuit from battery through the winding of relay 1204 Fig. 12, lower right-hand contact 1211 (4+5) of register 1100, conductor 1191, upper contact 1101 (2+5), 40 normal contacts 1111, 1121, 1131, etc., to conductor 1139, back contact and right-hand armature of relay 1606, upper right-hand contact 1616 (1+11), to ground. The function of relay 1204 in controlling the trans- 45 lator switch will be described in detail hereinafter. At the present stage of the connection the relay 1204 serves to advance the sequence switch 1600 out of position 2 and into position 3 by means of the following 50 circuit: ground through the outer left-hand armature and contact of said relay, conductor 1190, lower left-hand contact 1612 (1+16), upper right-hand contact 1612 (2), windings of sequence switch magnet 1600 55 to battery and ground.

With sequence switch 1600 in position 3 and the sender sequence switch 600 in position 12, the fundamental circuit is again established as follows: battery, through the 60 winding of relay 1607, lower right-hand contact 1611 (1+10), upper left-hand contact 1611 (3), conductor 1146, contact 1102, contact 1112 of register 1110 closed in its normal position, and thence over the normal 65 contacts 1122, 1132, etc., of the other regis- ters to conductor 1137, upper right-hand contact 1625 (1+11), inner left-hand armature and contact of relay 1603, conductor 768, lower right-hand contact 754 and contacts 730, conductor 155, 70 thence over the previously described circuit through the winding of stepping relay 601, returning by way of conductor 156, upper contacts 736 (3 to 13), lower right-hand contact 749, conductor 766, contact and 75 outer left-hand armature of relay 1603 to ground at lower contact 1618. Relay 1607 energizes and closes a substitute circuit for itself independent of the normal contact 1113 of register 1110, which is immediately 80 opened. This circuit may be traced from battery through the winding and contact and left-hand armature of relay 1607, upper left-hand contact 1625 (1+10), and thence over the fundamental circuit as traced. 85 Relay 1607 completes a circuit from battery through the winding of relay 1606, lower right-hand contact 1622, upper left-hand contact 1622 to ground at the contact and right-hand armature of relay 1607. Relay 1606 attracts its armatures and completes a driving circuit as follows for the second intermediate register 1110: battery, through the winding of said register, upper left-hand contact 1114 closed from position 90 N to position 9, lower left-hand contact 1613 (3), lower right-hand contact 1615, left-hand armature and contact of relay 1606, lower right-hand and upper left-hand contacts 1622 to ground at the right-hand armature of relay 1607. Register 1110 energizes 95 in this circuit and commences to rotate from its normal position N.

The stepping relay 601, which also energizes in the fundamental circuit, closes a 105 circuit over its armature and contact, conductor 614, upper contact 346, upper right-hand contact 609 (12) conductor 568, upper right-hand contact 413 of register 410 closed in position 5, conductor 417, armature and 110 back contact of relay 625, winding of relay 626 to battery and ground. Relay 626 energizes and prepares a locking circuit for itself and relay 625 in the manner described. As the register 1110 moves from one position to another, it closes at contact 1113 a 115 momentary circuit for the energization of relay 1607 in shunt of the stepping relay 601. This circuit may be traced from battery through the winding and contact and left-hand armature of relay 1607, upper contacts 1625, conductor 1137, upper contact 1113, first closed in position N $\frac{1}{2}$, conductor 1138, left-hand contacts 1630, front contact and right-hand armature of relay 1606, upper 120 right-hand contact 1616 to ground. When contact 1113 passes through positions O $\frac{1}{2}$, 1 $\frac{1}{2}$, etc., a circuit is again closed and for each of these closures stepping relay 601 is deenergized. At the first deenergization of 125 130

relay 601 relays 625 and 626 are locked up in a series and for each following deenergization an additional pair of counting relays are energized and locked up. After six 5 impulses have been transmitted to position the register 1110, the contact 1113 passes through position 4 $\frac{5}{8}$, the stepping relay 601 is shunted, and the O' counting relay 613 is operated. Relay 613 opens the fundamental 10 circuit and also completes a circuit over its contact and inner armature for driving the sender sequence switch 600 into position 13. The sequence switch 600 immediately moves into position 14 by means of a circuit over 15 the left-hand contact 604 (13), left-hand contacts 328 (8), conductor 371, conductor 447 (Fig. 4), and contact 408. The fundamental circuit having been opened at the sender in the originating office, relay 1607 20 releases as soon as its holding circuit is opened as sequence switch contact 1113 moves out of position 4 $\frac{5}{8}$. Relay 1607, on deenergizing, opens the driving circuit of register 1110, which thereby comes to rest 25 in position 5. Relay 1607 also opens the circuit of relay 1606, which, on releasing its armatures, completes a circuit as follows for driving the sequence switch 1600 out of position 3 and into position 4: battery, through 30 the winding of said sequence switch, lower left-hand contact 1619 (3), conductor 1147, upper contact 1111, lower normal contacts 1121, 1131, etc., in series to conductor 1139, back contact and right-hand armature of 35 relay 1606, upper right-hand contact 1616 to ground.

With the sender sequence switch 600 in position 14 and the control sequence switch 1600 in position 4, the fundamental circuit 40 including relays 1607 and 601 is again closed. This circuit may be traced from battery through the winding of relay 1607, lower right-hand contact 1611 (1+10), lower left-hand contact 1611 (4), conductor 45 1148 upper contact 1112, through the lower normal contacts 1122, 1132 etc. in series, conductor 1137, thence over the above traced path through the stepping relay 601 and contact 607, (14), returning over the other 50 side of the line to ground at the lower left-hand contact 1618 (1+10). Relay 1607 becomes energized and locks up over its contact and left-hand armature independently of the normal contact 1122 of the register 55 1120, which is about to be positioned. Relay 1607 again causes the energization of relay 1606 and this latter relay completes an operating circuit as follows for the third intermediate register 1120; battery, through 60 the winding of said register, upper left-hand contact 1124 (N+9), lower right-hand contact 1613 (4), lower right-hand contact 1615, left-hand armature and front contact of relay 1606 to ground at the contact and 65 right-hand armature of relay 1607. Reg-

ister 1120 thereupon commences to rotate and in passing from one position to another closes its short-circuiting contact 1123.

The stepping relay 601, on first energizing, closes a circuit through its armature and contact, conductor 614, upper contact 346, lower right-hand contact 609 (14), conductor 570, lower left-hand contact 423, (3) of register 420; conductor 416, armature and back contact of relay 621, winding 75 of relay 622 to battery and ground. In the manner well understood relay 622 operates and prepares a series circuit for relay 621. At each closure of the contact 1123, a circuit is established momentarily from battery through the winding of relay 1607 contact and left-hand armature of said relay, upper contacts 1625, conductor 1137, contact 1123, conductor 1138, left-hand contacts 1630 (1+10), front contact and right-hand armature of relay 1606, upper right-hand contact 1616 to ground. This direct circuit to ground shunts out the stepping relay 601, which releases for each closure thereof and permits the energization and 80 locking up of a pair of counting relays. In position 2 $\frac{5}{8}$ of the register 1120, said register having been advanced to a position corresponding to four impulses, the O' counting relay 613 operates, opens the fundamental 85 circuit and also closes the above traced circuit for advancing the sender sequence switch 600 out of position 14 and into position 1. Sequence switch 600, in passing from position 15 to position 1, closes 90 a circuit from battery through the winding of sequence switch magnet 300, conductor 373, upper contacts 605 (15+1), upper left-hand contact 326 (8) to ground. The cord 95 finder sequence switch 300 is energized in this circuit and moves from position 8 into position 15. The sender sequence switch 600, therefore, immediately passes from position 1 into position 2 on the closure of the following circuit: battery, through the 105 winding of sequence switch magnet 600, upper right-hand contact 603 (1), lower left-hand contact 326 (9+15) to ground.

As soon after the fundamental circuit is 110 opened at the sender in the originating office as the register 1120 leaves position 2 $\frac{5}{8}$, relay 1607 releases its armatures and opens the energizing circuit of said register and also the circuit of relay 1606. The register 1120 thereupon comes to rest in position 3 and 115 relay 1606 completes a circuit from battery through the winding of sequence switch magnet 1600, upper left-hand contact 1619 (4), conductor 1149, upper contact 1121, normal contacts 1131, 1141, etc., in series, conductor 1139, back contact and right-hand armature of relay 1606 to ground over the upper right-hand contact 1616. Sequence switch 1600 advances into position 5. That 120 portion of the total, designation that deter- 130

mines the routing of the call to the required office has thus been transferred from the originating office to the intermediate registers 1100, 1110, and 1120 at the tandem point.

- 5 The transfer of the numerical record follows immediately in the manner about to be discussed.

The fundamental circuit is again established from battery, through the winding of relay 1607, lower right-hand contact 1611, upper left-hand contact 1611 (5), conductor 1146, upper contact 1122, normal contacts 1132, 1142, etc., in series, conductor 1137, upper right-hand contact 1625, and thence, as 10 described, over the interoffice trunk 155, through the winding of stepping relay 601, lower contact 607 (2), conductor 359, right-hand contact 324 (9+15), and thence, as hereinbefore traced, over the other trunk conductor 156 (2) to ground at the lower left-hand contact 1618. Relay 1607 again causes the energization of relay 1606, which in turn completes a circuit for the operation of register 1130 as follows: battery, through the 15 winding of said register, upper left-hand contact 1134 (N+3), upper right-hand contact 1614 (5), lower right-hand contact 1615, left-hand armature and contact of relay 1606 to ground at the right-hand armature of relay 1607. Register 1130 rotates and in passing from one position to another causes a momentary closure of the short-circuiting contact 1133.

Stepping relay 601, upon energizing, closes 20 a circuit over its armature and contact, conductor 614, lower contact 346 (9+15), upper left-hand contact 610 (2), lower left-hand contact 504 (4+5) of register 500, conductor 571, armature and back contact of relay 623, 25 winding of relay 624 to battery and ground. Relay 624 operates and prepares a circuit for relay 623. In position N $\frac{5}{8}$ of register 1130, the following circuit is closed in shunt of the stepping relay 601: battery, through the 30 winding and contact and left-hand armature of relay 1607, upper contacts 1625, conductor 1137, contact 1133, (N $\frac{5}{8}$), conductor 1138 to ground as described over the upper right-hand contact 1616. Relay 601 is thereby 35 shunted and the first pair of counting relays are locked up. In position 1 $\frac{5}{8}$ of register 1130, the O' counting relay 613 becomes energized, opens the fundamental circuit and also closes a circuit for driving the sender sequence switch 600 out of 40 position 2 and into position 3. Sender sequence switch 600 immediately passes into position 4 by means of a circuit from battery through the winding of said sequence switch, 45 lower left-hand contact 602 (2+18), upper left-hand contact 602 (3), left-hand contact 329 (5+15) to ground.

After the fundamental circuit is opened and register 1130 reaches position 1 $\frac{5}{8}$, relays 50 1607 and 1606 become deenergized and the

driving circuit of said register is opened. Relay 1606 closes a circuit from battery through the winding of sequence switch magnet 1600, lower left-hand contact 1619 (5), conductor 1147, upper contact 1131, normal contacts 1141, 1151, etc., in series, conductor 1139, back contact and right-hand armature of relay 1606 to ground over the upper right-hand contact 1616 (1+11). Sequence switch 600 is thereby driven into position 6. 70

The fundamental circuit is closed once more in the manner already described and relays 1607, 601, and 1606, are operated. This time a driving circuit is established for the next register 1140, traceable from battery 80 through the winding of said register, upper left-hand contact 1144 (N+3), upper left-hand contact 1614 (6), lower right-hand contact 1615 (2+10), left-hand armature and contact of relay 1606 to ground at the 85 right-hand armature of relay 1607. With the sender sequence switch 600 in position 4, stepping relay 601 closes a circuit over its armature and conductor 614, lower contact 346, upper right-hand contact 610 (4), lower 90 contact 506 (4) of register 500, upper contact 514 (5+9) of register 510, conductor 445, armature and back contact of relay 615, winding of relay 616 to battery and ground. Relay 616 operates and prepares a circuit for 95 relay 615. On reaching position N $\frac{5}{8}$, register 1140 closes at its contact 1143 a circuit similar to the one already traced for shunting the stepping relay 601 in the fundamental circuit. Relay 601 releases its armature and 100 permits the energization of relay 615. The stepping circuit is now extended to the No. O counting relay 618, and on the next closure of contact 1143 in position O $\frac{5}{8}$, the O' counting relay 613 operates to open the fundamental 105 circuit and to close a circuit for driving the sender sequence switch out of position 4 and into position 5. Sequence switch 600 immediately advances from position 5 into position 6 over a circuit from battery 110 through the winding of said sequence switch, upper left-hand contact 603 (5), conductor 361 to ground at the lower contact 325 (9+16).

After the fundamental circuit has been 115 opened at the sender and register 1140 has moved out of position O $\frac{5}{8}$, relay 1607 retracts its armatures to open the driving circuit of said register and also the circuit of relay 1606. Register 1140, therefore, stops in position 1 while relay 1606 establishes a circuit from battery through the winding of sequence switch magnet 1600, upper left-hand contact 1619 (6), conductor 1149, upper contact 1141, normal contacts 1151, 1161, etc. in 120 series, conductor 1139, back contact and right-hand armature of relay 1606 to ground through the upper right-hand contact 1616. Sequence switch 1600 thereupon moves into 125 position 7. 130

With sequence switch 600 in position 6 and sequence switch 1600 in position 7, a fundamental circuit is established and relays 601, 1607, and 1606, are energized. A circuit for 5 register 1150 is now closed from battery through the winding of said register, upper left-hand contact 1154 (N+3) lower left-hand contact 1614 (7), lower right-hand contact 1615 to ground at the right-hand armature of relay 1607. The stepping relay 10 601 closes a circuit over conductor 614, lower contact 346, lower right-hand contact 610 (6), lower left-hand contact 515 (7) of register 510, conductor 571, armature and back 15 contact of relay 623, winding of relay 624 to battery and ground. Relay 624 operates and prepares a series circuit for relay 623. Register 1150, in passing positions N $\frac{5}{8}$, O $\frac{5}{8}$, etc., closes the shunt circuit, now well under- 20 stood, to cause the deenergization of the stepping relay 601. When the O' counting relay 613 is finally energized as the register 1150 reaches position 1 $\frac{5}{8}$, the fundamental circuit is opened and the sender sequence 25 switch 600 advances from position 6 to position 8. As contact 1153 opens after the fundamental circuit has been severed at the sender, relay 1607 releases to open the driving circuit of register 1150 and also the circuit 30 of relay 1606. Register 1150 stops in position 2 and relay 1606 closes a circuit as explained for advancing the control sequence switch 1600 from position 7 to position 8.

The fundamental circuit is again closed 35 and an operative circuit established for the register 1160, traceable from battery through the winding of said register, upper left-hand contact 1164 (N+9), lower right-hand contact 1614 (8), lower right-hand contact 1615 40 to ground at the contact and right-hand armature of relay 1607. With the sender sequence switch 600 in position 8 the stepping relay 601 closes a circuit over conductor 614, lower contact 346, lower left-hand contact 610 (8), upper right-hand contact 504 (5) of register 520, conductor 417, armature and back contact of relay 625, winding of relay 626 to battery and ground. Relay 626 operates and prepares a series circuit for relay 50 625. As the register 1160 rotates from one position to another, contact 1163 closes a shunt circuit around the winding of the stepping relay 601 and successive pairs of the counting relays in the originating office are 55 energized. The operation of the O' counting relay 613 opens the fundamental circuit, as explained, and completes a circuit for driving the sender sequence switch 600 out of position 8 and into position 9. Sequence 60 switch 600 immediately advances into position 10 over a circuit from battery, through the winding of said sequence switch, lower right-hand contact 603 (9), lower right-hand contact 326 (9+15) to ground. After 65 the fundamental circuit has been opened by

the relay 613 and register 1160 moves out of position 4 $\frac{5}{8}$, relays 1607 and 1606 are deenergized and the driving circuit of register 1160 is opened. Relay 1606 in the manner already described closes a circuit for moving 70 the control sequence switch 1600 out of position 8 and into position 9.

The fundamental circuit is again closed and an operative circuit established as follows for the register 1170: battery, through 75 the winding of said register, upper left-hand contact 1174 (N+9), upper right-hand contact 1615 (9), lower right-hand contact 1615 to ground at the contact and right-hand armature of relay 1607. The stepping relay 80 601 now closes a circuit over the conductor 614, lower contact 346, upper contact 611 (10), left-hand contact 534 (2) of register 530, conductor 571, armature and back contact of relay 623, winding of relay 624 to 85 battery and ground. Relay 624 energizes and prepares a series circuit for itself and relay 623. The rotation of register 1170 causes the momentary closure of contact 1173, and the consequent shunting of the 90 stepping relay 601 in the fundamental circuit. When register 1170 reaches position 1 $\frac{5}{8}$ and relay 601 is deenergized, the O' counting relay 613 operates to open the fundamental circuit and also to complete a circuit 95 for sending the sequence switch 600 out of position 10 and into position 11. Sequence switch 600 at once moves to position 12 by means of a circuit from battery through the winding of said sequence switch, 100 right-hand contact 604 (11), right-hand contacts 328 (9+15), conductor 374, thence to conductor 448, Fig. 4, upper left-hand contact 508 (3) of sequence switch 400 to ground. Following the opening of the fundamental circuit at the sender, register 1170 leaves position 1 $\frac{5}{8}$ and relays 1607 and 1606 are deenergized. Relay 1607 opens the driving circuit of register 1170 and the latter comes to rest in position 2. Relay 1606 completes a circuit already described for moving 110 the control sequence switch 1600 out of position 9 and into position 10.

The fundamental circuit is established for the last time with sender sequence switch 115 600 in position 12, and the control sequence switch 1600 in position 10, and relays 1607, 601, and 1606 are operated. An operating circuit is now established for register 1180 from battery through the winding of said 120 register, upper right-hand contact 1184 (N+5), upper left-hand contact 1615 (10), lower right-hand contact 1616 to ground at the right-hand armature of relay 1607. Stepping relay 601 at the sender closes a circuit 125 over conductor 614, lower contacts 346, lower contact 611 (12), upper right-hand contact 544 (5), of register 540, conductor 417, armature and back contact of relay 625, winding of relay 626 to battery and ground. 130

For each momentary closure of the contact 1183 as register 1180 advances from position to position, relay 601 is shunted and a pair of counting relays are operated and locked up. When finally the O' counting relay 613 energizes, the fundamental circuit is opened and the sender sequence switch 600 driven from position 12 to position 13. Relay 1607 also deenergizes opening the driving circuit 5 of register 1180 and the circuit of relay 1606. Relay 1606, on releasing, closes a circuit from battery, through the winding of sequence switch magnet 1600, upper left-hand contact 1619 (10), conductor 1149, upper 10 contact 1181, conductor 1139, back contact and right-hand armature of relay 1606 to ground over the upper right-hand contact 1616. Sequence switch 1600 thereupon moves into position 11.

20 *Restoration of cord finder and register sender.*

In position 13 of the sender sequence switch 600, a circuit is established for advancing the district sequence switch 100 out of position 11 and into position 12. This circuit may be traced from battery through the winding of said sequence switch, upper left-hand contact 144 (11+17), lower left-hand contact 144 (11), conductor 362, terminal 317, brush 311, upper left-hand contact 606 (13), lower right-hand contact 326 (9+15) to ground. Sequence switch 100 immediately advances into position 14 by means of a circuit from battery through the windings of said sequence switch, upper left-hand contact 142 (12+13), back contact and left-hand armature of relay 119, upper right-hand contact 142 (12+13) to ground. The 30 interrupting circuit of lamp 121, which has been flashing up to this time, is opened as sequence switch 100 leaves position 11, and in position 14 the following circuit is closed for the steady illumination of the lamp; battery, resistance 161, lamp 121, upper right-hand contact 149 (14), lower left-hand contact 149 (12+16) to ground. This change from a flashing to a steady signal informs the operator that the register sender has 45 completed its functions and is about to be disassociated from the cord circuit.

Sequence switch 100, on reaching position 11, opens at its lower left-hand contact 145 the circuit hereinbefore traced for relay 302. 55 Relay 302 completes a circuit from battery through the winding of the cord finder sequence switch 300, upper left-hand contact 335 (8+16), back contact and right-hand armature of relay 302 to ground to drive 60 said sequence switch out of position 15 and into position 17. The sender sequence switch 600 is now driven to its normal position 1, by means of a circuit from battery through the winding of said sequence switch, lower left-hand contact 602 (2+18), lower

right-hand and upper left-hand contacts 330, back contact and right-hand armature of relay 302 to ground.

After the operator has received the number of the wanted line from the calling subscriber she may, if she desires, listen out by depressing the key 213. The operation of key 213 closes a circuit from ground over its contacts and the lower right-hand contact 212 (7), of sequence switch 200 to drive that 70 sequence switch into position 11, the listening out position. If, however, the operator does not actuate the key 213, sequence switch 200 remains in the listening in position 7 and is later driven therefrom, automatically, in the manner about to be described. Assuming that the sequence switch 200 has remained in position 7 during the functioning of the register sender, a circuit is closed by the sender sequence switch 600 80 reaching its normal position at the completion of the second revolution. This circuit may be traced from battery through the winding of sequence switch magnet 200, lower right-hand contact 212 (7), conductor 85 214, back contact and left-hand armature of relay 303, lower right-hand contact 602 (1), lower right-hand and upper left-hand contacts 330 (17), back contact and right-hand armature of relay 302 to ground. Sequence 90 switch 200 thereby moves from position 7 into position 11. Sequence switch 200, on reaching position 7 $\frac{1}{4}$, completes a circuit from ground over contact 209 (7 $\frac{1}{4}$ +10 $\frac{1}{2}$), conductor 215, right-hand normal contact 95 of relay 303, winding of said relay, lower left-hand contact 349 (2+17), to battery and ground. Relay 303 becomes energized and locks up over its right-hand armature and make-before-break contact, independent 100 of sequence switch contact 209. Relay 303 completes a circuit from battery through the winding of the downdrive power magnet 306, front contact and left-hand armature of relay 303, lower right-hand contact 602 (1), 105 lower right-hand and upper left-hand contacts 303, back contact and right-hand armature of relay 302 to ground. The power magnet 306 operates to restore the brush shaft of the cord finder 350 to its normal 110 position. In the normal position of the cord finder switch a circuit is completed from battery through the winding of the sequence switch magnet 300, upper left-hand contact 336 (8+17), normal position segment 322, 115 brush 320 to ground, whereby sequence switch 300 moves into position 18. This cord finder switch is now ready to be allotted by the allotter 310 for subsequent use.

It will be recalled that the control sequence 125 switch 1600 moved into position 11 following the transfer of the last digit of the wanted number and that shortly thereafter the district sequence switch 100 at the originating office advanced from position 11 into 130

position 14. As sequence switch 100 reaches position 12 a circuit is closed from battery through the winding of relay 1601, upper contacts 1611 (11), conductor 1146, upper 5 contact 1182, conductor 1137, upper right-hand contact 1625 (1+11), inner left-hand armature and contact of relay 1603, conductor 768, lower right-hand contact 754 (1), lower and upper contacts 730, conductor 155, 10 terminal 136, brush 133, upper right-hand contact 153 (9+11), upper left-hand contact 153 (12+16), lower contact 208 (8+1), upper right-hand winding of repeating coil 112 to ground. Relay 1601 operates and 15 closes a circuit from battery through the winding of relay 1607, armature and contact of relay 1601, upper right-hand contact 1613 (11), lower left-hand contact 1615 (11) to ground. Relay 1607, over its contact and left-hand armature, locks up independently of the relay 1601. Relay 1607, which operates at this time by reason of the fact that the district sequence switch in the originating office has reached its trunk 20 closing position, serves later on, as will be described, as an indication at the tandem office that trunk closure has taken place at the originating office and insures the advances of the district switch in the tandem office in case the call is abandoned and the connection broken down at the originating office.

Operation of the translator switch and registration of the office designation.

It will be remembered that relay 1204 was energized in response to the release of relay 1606 immediately following the setting of the first register 1100. Since register 1100 is set in position 5 a circuit was also closed at this time from battery through the winding of relay 1106 Fig. 11, contact 1125 of register 1120 closed in its normal position, conductor 1199, upper left-hand contact 1211 40 (5), conductor 1191, upper contact 1101 (2+5), normal contacts 1111, 1121, etc. in series, conductor 1139, back contact and right-hand armature of relay 1606, upper right-hand contact 1616 to ground. Relays 45 1204 and 1106 both lock up in a parallel circuit, one branch of which extends from battery through winding and contact and inner left-hand armature of relay 1204 to conductor 1198, and the other branch extending 50 from battery through the winding and contact and left-hand armature of relay 1106, conductor 1198, and thence to ground over the upper left-hand contact 1616 (2+18). When the first three registers 1100, 1110, 55 1120 have been positioned and sequence switch 1600 arrives in position 5, the operation of the translator switch is proceeded with and the office designation recorded upon the relay registers of the tandem office reg-

ister sender without waiting for the completion of the transfer of the numerical record.

Accordingly, in position 5 of sequence switch 1600 a circuit is established from battery through the winding of the register magnet 1100, upper right-hand contact 1105 (1+5), conductor 1136, left-hand contacts 1509 of the sender sequence switch 1500, Fig. 15, lower right-hand contact 1612 (5+12), lower left-hand contact 1612 (1+16), conductor 1190, contact and outer right-hand armature of relay 1204 to ground. The register 1100 becomes energized in this circuit and moves from position 5 into position 6. In position 6 the relay 1201 is energized in a circuit from battery through the winding of said relay, conductor 1256, upper left-hand contact 1108 (6) to ground. Relay 1201 establishes a circuit from ground through its left-hand armature and front contact, upper contact 1210 (6), conductor 1192, upper right-hand contact 1104 (6), winding of register magnet 1100 to battery and ground. Register 1100 advances into position 7 and relay 1201 remains energized in a circuit from battery through the winding and contact and right-hand armature of said relay, contact and left-hand armature of relay 1200, conductor 1255, upper right-hand contact 1108 (6+11) to ground. A circuit is also closed in this position from battery through the winding of the updrive power magnet 1218 of translator switch 1260, contact and outer right-hand armature of relay 1204, lower contact 1210 (7), front contact and left-hand armature of relay 1201 to ground. Power magnet 1218 causes the upward movement of the brush shaft to select the proper one of the five sets of brushes. The first group of five segments 1271 on the commutator strip are 105 the brush selecting segments and a ground potential is placed on one or another of these, depending upon the position taken by the second intermediate register 1110. For the particular office code being considered 110 the register 1110 is standing in position 5. When, therefore, the hunting brush 1231 engages the third brush selecting segment 1272, a circuit is completed from battery through the winding of relay 1200, lower 115 right-hand and upper left-hand contacts 1109 (6 $\frac{3}{4}$ +7), conductor 1258, brush 1231, segment 1272, conductor 1156, lower right-hand contact 1117 (4+5) of register 1110, upper right-hand contact 1128 (6 $\frac{3}{4}$ +7) to ground. Relay 1200 becomes energized in this circuit and closes a holding circuit for itself over its right-hand armature and contact to ground through the lower right-hand contact 1107 (7). Relay 1200 also opens the circuit of relay 1201, which latter relay releases its armatures and opens the circuit of the updrive power magnet 1218. Relay 125

1201, on deenergizing, completes a circuit from ground through its left-hand armature and back contact, conductor 1193, upper left-hand contact 1104 (7), winding of register magnet 1100 to battery and ground, driving said register out of position 7 and into position 8. In position 8 the lower right-hand contact 1107 is opened and relay 1200 releases its armatures. A circuit is also closed at this time from battery through the winding of trip magnet 1220, upper right-hand contact 1273 to ground at the contact and inner right-hand armature of relay 1204. Magnet 1220 operates and positions the trip spindle for tripping the selected set of brushes on the next upward movement of the brush shaft.

It was stated hereinbefore that a section of forty terminals in the bank of the translator switch to which a set of brushes has access is divided into two groups of twenty, each of which groups is further subdivided into two groups of ten terminals. The nature of these divisions is illustrated in the grouping of the hunting segments on the commutator plate. The first group of twenty terminals of each section is represented by the hunting segments 1235, and the second group of twenty terminals by the hunting segments 1236. Both groups 1235 and 1236 are divided into the two groups of ten, as indicated, only a portion of each of such groups being shown in the drawing. The particular group of forty terminals in which the selected set of brushes is to hunt is determined by the position of the register 1100. Since in the present case the register 1100 is adjusted to position 5, relay 1106 is operated to determine that the selected set of brushes shall pass over the first group of twenty terminals and hunt in the second group of twenty, as will presently be seen.

When register 1100 reaches position 8 a circuit is closed from battery through the winding of relay 1201, conductor 1256 upper left-hand contact 1108 (8) to ground. Relay 1201 becomes energized and locks up over its contact and right-hand armature, and contact and left-hand armature of relay 1200 to ground at the upper right-hand contact 1108. Relay 1201 also closes a circuit from ground through its left-hand armature and front contact and upper contact 1210 (8), conductor 1192, the upper right-hand contact 1104 (8) for driving the register 1100 into position 9. The updrive power magnet 1218 is now energized and the selected set of brushes are driven over the terminal bank. The circuit for magnet 1218 may be followed from battery through the winding of said magnet, contact and outer right-hand armature of relay 1204, lower contact 1210 (9) to ground at the front contact and left-hand armature of relay 1201. After the hunting brush 1231 has traversed the entire twenty segments 1235, representing the first group of twenty sets of terminals in the terminal bank, it engages the first segment 1274 of the second group. A circuit is thereupon closed from ground through the upper left-hand contact 1128 (8+9), right-hand armature and front contact of relay 1106, conductor 1157, segment 1274, brush 1231, conductor 1258, upper left-hand and lower right-hand contacts 1109, winding of relay 1200 to battery and ground. Relay 1200 operates and closes a locking circuit for itself as above described. Relay 1200 also opens the circuit of relay 1201 but this latter relay remains energized by means of a circuit from battery through the winding and contact and right-hand armature of relay 1201, commutator 1232, brush 1233, upper left-hand contact 1273 to ground at the contact and inner right-hand armature of relay 1204. When the translator brushes 1221, 1222, 1223, 1224, and 1225 are accurately centered on the first set of terminals in the second group of twenty, brush 1233 engages an insulating segment of commutator 1232 and the holding circuit of relay 1201 is opened. Relay 1201, therefore becomes deenergized and opens the driving circuit of the power magnet 1218 to arrest the movement of the switch. Relay 1201 also closes a circuit from ground through its left-hand armature and back contact, conductor 1193, upper left-hand contact 1104 (9), for driving register 1100 out of position 9 and into position 10. In this position relay 1200 is again deenergized.

The second group of twenty terminals having been thus selected, there remains to determine which of the two sub-groups of ten the switch shall hunt in for the desired set of terminals. This selection of one or the other of the two sub-groups of ten is governed by the second register 1110. If this register is in an even position the lower contact 1116 is closed, but if the register takes up an odd position the upper contact 1116 is closed instead. As will become clear in the following description, the position of contact 1116 determines whether the translator brushes hunt in the first or the second group of ten sets of terminals. In position 10 of register 1100, relay 1201 is again energized over the upper left-hand contact 1108 and locks up over the contact and left-hand armature of relay 1200 and the upper right-hand contact 1108 (6+11). Relay 1201, at its left-hand armature and front contact, closes a circuit including the upper contact 1210 (10), and the upper right-hand contact 1104 (10), for driving the register 1100 into position 11. In this position the updrive

power magnet 1218 is energized to elevate the brushes of the translator switch in search of the proper set of terminals. The circuit for magnet 1218 leads over the outer right-hand armature of relay 1204, lower contact 1210 (11) to ground at the front contact and left-hand armature of relay 1201. During the movement of brush 1231 over the first group of 10 segments, which are connected to contacts 1166, 1167, and 1168 in the several closing positions of register 1120, no ground potential is found since the lower contact 1116 of register 1110 is opened in all even positions. The movement of the switch, therefore, continues and the hunting brush 1231 enters the second group of ten terminals. When brush 1231 reaches terminal 1237, a circuit is established from battery through the winding of relay 1200, lower right-hand and upper left-hand contacts 1109 ($10\frac{3}{4}$ +11), conductor 1258, brush 1231, segment 1237, conductor 1169, lower left-hand contact 1127 (3) of register 1120, upper contact 1116 (5), upper right-hand contact 1107 ($10\frac{3}{4}$ +11) to ground. Relay 1200 operates and locks up, as explained, over the lower right-hand contact 1107. Relay 1200, at its left-hand armature, opens the circuit of relay 1201. As soon as the brushes 1221, 1222, 1223, 1224, and 1225 are accurately centered on the terminals 1226, 1227, 1228, 1229, and 1230, brush 1233 engages an insulating segment of commutator 1232 and relay 1201 releases its armatures to open the circuit of the updrive power magnet 1218. Relay 1201 also completes a circuit over its left-hand armature and back contact, conductor 1193, and upper left-hand contact 1104, for driving the register 1100 from position 11 into position 13.

In this position the register contacts 1212, 1213, 1214, 1215, and 1216 close the impulse leads from the impulse machine 1270 through to the relay register shown in Fig. 45 13. The circuits are so arranged as to insure a complete revolution of the impulse machine 1270 to enable the relay registers to take their proper settings before the register 1100 advances out of position 13 to 50 disconnect said impulse machine. It does not matter what point in its revolution the impulse machine happens to be in at the time it is connected through to the registers, but for simplicity it will be assumed that 55 the rotating drum and the cooperating brushes are in the relation illustrated in the drawing. Following the closure of the impulse leads the brushes to the impulse machine engage the first vertical row of 60 metallic segments. When this happens a circuit is closed from ground through the winding of relay 1205, lower left-hand and upper right-hand contacts 1109 (13), conductor 1259, brush 1238, segment 1275, segment 65 1249, brush 1244 to battery and

ground. Relay 1205 completes a circuit from ground over its armature and contact, conductor 1267, upper left-hand contact 1526 (1), lower right-hand contact 1526 (1+2), upper left-hand contact 1527 (1), contact and armature of relay 1503, winding of the stepping relay 1506, upper contact 1514 (17 + 1) to battery and ground. Relay 1506 becomes energized in this circuit and closes a circuit from ground through the lower right-hand contact 1520, contact and armature of relay 1506, upper right-hand contacts 1521 (1), upper left-hand contact 1521 (1+12), lower right-hand contact 1623 (5+14), upper left-hand contact 1623 (5+12), upper left-hand contact 1510 (1), conductor 1534, thence to conductor 1537, armature and back contact of the No. 2' counting relay 1538, winding of the No. 2 counting relay 1539, lower left-hand contact 1514 (1+2) to battery and ground. Relay 1539 attracts its armature and completes a circuit from battery through the lower left-hand contact 1514, windings of relays 1539 and 1538 in series, contact and armature of relay 1539, lower right-hand contact 1517 (1+2), upper left-hand contact 1517 (1), conductor 1257, lower left-hand contact 1108 (12+13) to ground. Relay 1538, however, does not energize at this time since its winding is shunted out by the direct circuit to ground through the armature and contact of the stepping relay 1506. With the brushes of the impulse machine in engagement with the first vertical row of segments, the following circuits are established: battery, segment 1276, brush 1241, terminal 1226, brush 1221, contacts 1212 (12 $\frac{3}{4}$ +13), winding of relay 1301 to ground; battery, segment 1277, brush 1239, terminal 1228, brush 1223, contacts 1214, winding of relay 1303 to ground; battery segment 1278, brush 1242, terminal 1229, brush 1224, contacts 1215, winding of relay 1304 to ground, and battery, segment 1279, brush 1243, terminal 1230, brush 1225, contacts 1216, winding of relay 1305 to ground. Relays 1301, 1303, 1304, and 1305 become energized in these circuits and close circuits respectively for the energization of relays 1306, 1308, 1309, and 1310. At the same instant that these relays are operated, the brush 1246 of the impulse machine is making contact with the first position segment 1252. A circuit is therefore established from battery over segment 1252, brush 1246, conductor 1329, inner right-hand armature and contact of relay 1306, conductor 1330, right-hand winding of relay 1402 to ground. Relay 1402 operates and locks up in a circuit through its left-hand winding and contact and armature, conductor 1264, upper contact 1207, contact and inner right-hand armature of relay 1202, conductor 1262, lower left-hand contact 1107 130

(6+18) to ground. Another circuit is closed from battery over conductor 1329, inner left-hand armature and contact of relay 1308, right-hand winding of relay 1317 to ground. This relay attracts its armature and closes a holding circuit for itself from battery through its left-hand winding and contact and armature, conductor 1331 to ground at the contact and inner right-hand armature of relay 1610. It is to be noted that relay 1610 energizes in a circuit including the upper right-hand contact 1620 when the control sequence switch 1600 reaches position 5. Another circuit is completed from battery over the conductor 1329, inner left-hand armature and contact of relay 1309, right-hand winding of relay 1323 to ground. Relay 1323 operates and closes a holding circuit for itself from battery through its left-hand winding and contact and armature, conductor 1332 to ground at the contact and outer right-hand armature of relay 1610. Still another circuit is closed in the first position of the impulse machine from battery over the conductor 1329, inner left-hand armature and contact of relay 1310, right-hand winding of relay 1327 to ground. Relay 1327 becomes energized and closes a holding circuit for itself from battery through its left-hand winding and contact and armature, conductor 1333, contact and outer left-hand armature of relay 1610 to ground.

As the brushes of the impulse machine disengage the first position segments, relays 1301, 1303, 1304, 1305, 1306, 1308, 1309, and 1310 retract their armatures. At the same instant brush 1238, on disengaging segment 1275, opens the circuit of relay 1205, which in turn deenergizes and opens the circuit of the stepping relay 1506. Relay 1506 releases its armatures and removes the shunt around the winding of the No. 2' counting relay 1538. Relay 1538, therefore, becomes energized and locks up in series with relay 1539. The impulse machine continues to rotate and the brushes presently engage the second position segments in the respective rows. A plurality of circuits are now established as follows: battery, segment 1280, brush 1241, terminal 1226, brush 1221, contacts 1212, winding of relay 1301 to ground; battery, segment 1281, brush 1240, terminal 1227, brush 1222, contacts 1213, winding of relay 1302 to ground; battery, segment 1282, brush 1239, terminal 1228, brush 1223, contacts 1214, winding of relay 1303 to ground, and battery, segment 1283, brush 1242, terminal 1229, brush 1224, contacts 1215, winding of relay 1304 to ground. Relays 1301, 1302, 1303, and 1304 close energizing circuits respectively for relays 1306, 1307, 1308, and 1309. At the same instant that these relays are energized, brush 1247 is engaging the second position segment 1253. A circuit is therefore established from battery through segment 1253, brush 1247, conductor 1334, inner left-hand armature and contact of relay 1306, conductor 1335, right-hand winding of relay 1403 to ground. Relay 1403 becomes energized and closes a holding circuit through its left-hand winding to the grounded conductor 1264. A circuit is also closed from battery over conductor 1334, inner right-hand armature and contact of relay 1307, left-hand winding of relay 1312 to ground. Relay 1312 attracts its armatures and closes a holding circuit for itself from battery through its right-hand winding and contact and inner right-hand armature, conductor 1336, contact and inner left-hand armature of relay 1610 to ground. Another circuit is closed from battery over conductor 1334, inner right-hand armature and contact of relay 1308, left-hand winding of relay 1316 to ground. Relay 1316 operates and closes a holding circuit for itself from battery through its right-hand winding and contact and inner right-hand armature to the grounded conductor 1331. Still another circuit is completed from battery over the conductor 1334, inner right-hand armature and contact of relay 1309, left-hand winding of relay 1324 to ground. Relay 1324 operates and locks up over its right-hand winding through the grounded conductor 1332. When the impulse machine rotates to a point where the brushes disengage the second position segment, relays 1301, 1302, and 1303, etc. again become deenergized.

In the third position of the impulse machine, brush 1238 engages the segment 1284 and current is supplied over conductor 1259 to operate relay 1205. Relay 1205 again closes the above traced circuit for the energization of the stepping relay 1506. Relay 1506 this time extends the stepping circuit over conductors 1534 and 1537, armature and front contact of relay 1538, armature and back contact of relay 1540, winding of relay 1541, lower right-hand contact 1514 (1+2) to battery and ground. Relay 1541 attracts its armature and prepares a series circuit for itself and relay 1540. Relay 1540, however, being shunted by a direct circuit to ground through the armature of the stepping relay 1506, remains inert. With the brushes of the impulse machine in engagement with their third position segments, the following circuits are established: battery, segment 1285, brush 1241; terminal 1226, brush 1221, and thence to ground through the winding of relay 1301, and battery, segment 1286, brush 1242, terminal 1229, brush 1224, and thence to ground through the winding of relay 1304. Relays 1301 and 1304 become energized and complete operating circuits for relays 1306 and 1309, respectively. At the same instant that relays 1306 and 1309 are being maintained energized, the brush 130

1248 is making contact with third position segment 1254. A circuit is therefore closed from battery through the segment 1254, brush 1248, conductor 1337, outer left-hand 5 armature and contact of relay 1306, conductor 1338, right-hand winding of relay 1404 to ground. Relay 1404 operates and closes a holding circuit for itself through its left-hand winding and contact and armature 10 to the grounded conductor 1264. Another circuit is closed from battery over conductor 1337, outer right-hand armature and contact of relay 1309, left-hand winding of relay 1339 to ground. Relay 1339 closes a circuit 15 for itself from battery through its right-hand winding and contact and inner armature to the grounded conductor 1331. As the brushes of the impulse machine 20 disengage the third position segments, relays 1301, 1304, 1306, and 1309 become deenergized. At the same time relay 1205 retracts its armature and opens the energizing circuit of the stepping relay 1506. Relay 1506 deenergizes and removes the short- 25 circuit from around the winding of the counting relay 1540. Relay 1540 thereupon energizes in series with relay 1541. When the impulse machine has made a complete revolution and its brushes engage the last 30 position segments, a circuit is again closed from battery over segment 1287, brush 1238, conductor 1259 to ground through the winding of relay 1205. Relay 1205 operates and closes the above traced circuit for the stepping relay 1506. This relay closes the stepping circuit from ground over conductors 1534 and 1537 armature and front contact 35 of relay 1538, armature and front contact of relay 1540, conductor 1535, conductor 1542, left-hand armature and back contact 40 of relay 1504, winding of relay 1501 to battery and ground. Relay 1501 becomes energized, and prepares a circuit as follows for relays 1502 and 1503: battery, through the 45 winding of relay 1501, thence in parallel through the windings of relays 1502 and 1503, contact and armature of relay 1501, lower right-hand contact of relay 1517 (1+2), upper left-hand contact of relay 1517 (1), 50 to ground as described over conductor 1257. Relays 1502 and 1503, however, do not energize since they are shunted out by the stepping relay 1506. With the impulse machine in its last position of rotation, the following circuits are established: battery, segment 1288, brush 1239, terminal 1228, brush 1223 and thence to ground through the winding of relay 1303; battery, over the segment 1289, brush 1242, terminal 1229, brush 1224, 55 and thence to ground through the winding of relay 1304, and battery, through segment 1290, brush 1243, terminal 1230, brush 1225 to ground through the winding of relay 1305. Relays 1303, 1304, and 1305 energize 60 in these circuits and close operating circuits for relays 1308, 1309, and 1310 respectively. At the same time that these latter relays are being maintained energized, the brush 1245 engages the fourth position segment 1251 and a circuit is extended from 65 battery over conductor 1340, outer left-hand armature and contact of relay 1308, right-hand winding of relay 1318 to ground. Relay 1318 locks up over its left-hand winding through the grounded conductor 1331. Relay 1318 also, at its right-hand armature and contact, closes an energizing circuit for relay 1319. Another circuit is completed from 70 battery over conductor 1340, outer left-hand armature and contact of relay 1309, right-hand winding of relay 1321 to ground. Relay 1341 operates and closes a holding circuit through its left-hand winding and contact and armature to the grounded conductor 1332. Relay 1331 also closes a circuit 75 at its right-hand armature and contact for the energization of relay 1322. Still another circuit is completed from battery over the conductor 1340, outer left-hand armature and contact of relay 1310, right-hand winding of relay 1325 to ground. Relay 1325 locks up over its left-hand winding to the grounded conductor 1333. This relay furthermore closes the circuit of its right-hand armature and contact for the energization of 80 relay 1326. The office registers of the tandem office sender have now been positioned to record the office designation by means of a code of impulses generated by the impulse machine and transmitted through the translator switch. 85 When the brush 1238 of the impulse machine disengages segment 1287, relay 1205 is deenergized and opens the circuit of the stepping relay 1506. Relay 1506 retracts its 90 armature and removes the shunt from around the winding of relays 1502 and 1503 and these relays become energized in series with relay 1501. Relay 1503 attracts its armature and opens the circuit over which relay 1506 was 95 energized. Relay 1502 completes a circuit from ground through its armature and contact, contacts 1522 (1+12), conductor 1195, upper left-hand contact 1105 (13), winding of register magnet 1100 to battery and ground. 100 Register 1100 leaves position 13 and moves into position 15. As the register 1100 reaches position 13 $\frac{3}{4}$, a circuit is closed for putting the class sequence switch 1400 in a position corresponding to the particular combination 105 of relays 1401, 1402, 1403, and 1404 that have been energized from the impulse to determine the class of the call that is being made. The sequence switch 1400 has no normal position and may, therefore, be standing in 110 any one of its positions from 1 to 17. It will be assumed that position 10 of the class sequence switch is the position in which full 115

mechanical connections are extended, such as the one being considered herein. It will also be assumed that sequence switch 1400 happens to be standing in position 16 at this time. Hence since relays 1402, 1403, and 1404 are attracted and relay 1401 is deenergized when the register 1100 reaches position 13 $\frac{3}{4}$, a circuit is closed from battery through the winding of sequence switch magnet 1400 5 lower left-hand contact 1405 (16), front contact and right-hand armature of relay 1403, conductor 1266, upper left-hand contact 1206 (13 $\frac{3}{4}$ +15), contact and inner right-hand armature of relay 1202, conductor 1262, lower 10 left-hand contact 1107 (6+18) to ground. Sequence switch 1400 is energized in this circuit and moves out of position 16 and into position 17 where a circuit is closed from battery through the winding of said sequence 15 switch, upper left-hand contact 1406 (17), back contact and right-hand armature of relay 1401 to the grounded conductor 1266. Sequence switch 1400 advances into position 20 1 where the same circuit is established over the left-hand contact 1406 to advance said sequence switch out of position 1 and into position 2. In this position a circuit is closed from battery through the winding of sequence switch 1400, upper right-hand contact 1406 (2), front contact and right-hand armature of relay 1402 to the grounded conductor 1266. The sequence switch 1400 advances into position 3 and from here it is advanced through the successive positions by 25 means of the circuits described alternately closed through the upper left-hand and upper right-hand contacts 1406. On reaching position 10 it will be noted from inspection of the drawing that no circuit is found for advancing the sequence switch out of this position. It will be observed that during the movement of the class sequence switch 1400, the relay 1410 is maintained energized in parallel to the circuit of said sequence switch. As soon as sequence switch 1400 reaches position 10, relay 1410 becomes deenergized and completes a circuit from ground through its armature and contact, contact 1411 (9+7), conductor 1194, lower left-hand contact 1104 (15), 30 winding of register magnet 1100 to battery and ground. Register 1100 moves from position 15 into position 16 and a circuit is completed as follows for advancing the sender sequence switch 1500 out of position 1 and into position 2, battery, through the winding of said sequence switch, lower left-hand contact 1524 (1), conductor 1261, lower right-hand contact 1128 (16) to ground. With the sender sequence switch 1500 in position 2 a 35 circuit is completed from battery through the winding of register magnet 1100, lower left-hand contact 1105 (16), conductor 1196, back contact and left-hand armature of relay 1202, upper and lower contacts 1209, conductor 1268, lower left-hand contact 1516 65 (2+18), upper right-hand contact 1517 (2+18), to ground. The register 1100 thereby moves from position 16 into position 18. 40

Release of translator switch.

In position 18 of register 1100 the translator switch 1260 is restored to its normal position by the downdrive power magnet 1219. The operating circuit for this magnet may be traced from battery through the 75 winding thereof, lower right-hand contact 1273 (18), contact and inner right-hand armature of relay 1204 to ground. After the brush shaft reaches its normal position, a circuit is established from battery through 80 the winding of register magnet 1100, conductor 1263, lower contacts 1208 (18), normal position segment 1234, brush 1233, upper left-hand contact 1273 to ground at the contact and inner right-hand armature of relay 85 1204. Register 1100 thereupon moves from position 18 to its normal position 1 and the circuit of the downdrive power magnet 1219 is opened. 90

Operation of tandem district switch.

When the sender sequence switch 1500 reaches position 2 a circuit is closed from battery through the winding of relay 1501, windings of relays 1502 and 1503 in parallel, 95 lower left-hand contact 1525 (2+13), upper right-hand contact 1525 (2), upper right-hand contact 1628 (5+12) to ground. These relays become energized and a circuit is closed from ground through the armature 100 and contact of relay 1502, contacts 1522 (1+12), upper right-hand contact 1523 (2), winding of sequence switch magnet 1500 to battery and ground, advancing said sequence switch out of position 2 and into position 4. 105 As the sequence switch leaves position 2 the upper right-hand contact 1525 is opened to permit the deenergization of relay 1502 before said sequence switch reaches position 4. In position 4 of the sender sequence switch 110 the fundamental circuit is established for controlling the brush selecting operation of the district switch in the tandem office. This circuit may be traced from battery through right-hand winding of relay 701, lower left-hand contact 745 (7), lower right hand contact 746 (7+10), lower right-hand contact 751 (1), conductor 769, contact and inner right-hand armature of relay 1604, lower right-hand contact 1633 (5+17), lower left-hand contact 1633 (5+12), right-hand contacts 1509 (2+6), winding of the stepping relay 1506, armature and contact of relay 1503, upper contact 1527 (4), right-hand contacts 1526 (4) to ground at the upper 115 right-hand contact 1628 (5+12). Relay 701 becomes energized and closes a circuit from battery through the winding of sequence 120

125

- switch magnet 700, lower left-hand contact 743 (7), front contact and left-hand armature of relay 701, left-hand contacts 739 to ground, driving sequence switch 700 out of position 7 and into position 8. In position 8 the relay 701 is maintained energized through a circuit from battery through its right-hand winding and contact and inner right-hand armature, lower left-hand contact 744 (2+13), lower right-hand contact 746 (7+10), and thence, as described, over the fundamental circuit to ground. The up-drive power magnet 709 is now energized and causes the upward movement of the district switch 750. The circuit for this magnet may be traced from battery through the winding thereof, lower contact 742 (8), front contact and left-hand armature of relay 701 to ground at contact 739.
- 20 Stepping relay 1506 also energizes in the fundamental circuit and closes a circuit from ground, lower contact 1520 (4), contact and armature of relay 1506, upper right-hand contact 1521 (4), upper left-hand contact 1521 (1+12), lower right-hand contact 1623 (5+14), upper left-hand contact 1623 (5+12), lower left-hand contact 1510 (4), conductor 1543, contact and outer right-hand armature of relay 1202, conductor 1544, contact 1409 (9+7), right-hand armature and back contact of register relay 1313, outer right-hand armature and contact of relay 1312, conductor 1314, thence to conductor 1537, Fig. 15, armature and back contact of relay 1538, winding of relay 1539, lower left-hand contact 1514 (4) to battery and ground. No. 2 counting relay 1539 operates in this circuit and prepares a series circuit through its winding and the winding 40 of relay 1538, contact and armature of relay 1539 to ground at the right-hand contact 1517. Relay 1538, however, being shunted by the stepping relay 1506, does not attract its armature. As the district selector 750 approaches its first brush tripping position, brush 718 engages a metallic segment of commutator 713, and a circuit is closed from battery through the winding and contact and inner right-hand armature of relay 701, lower contact 744, upper right-hand contact 745 (7₄+8), commutator 713, brush 718 to ground. This direct circuit to ground shunts the stepping relay 1506 in the fundamental circuit, which releases its armature 50 and removes the short-circuit from around the counting relay 1538. Relay 1538 thereupon energizes in series with relay 1539. As brush 718 disengages the metallic segment of commutator 713, relay 1506 becomes energized and the stepping circuit is now closed by way of conductor 1537, armature and front contact of relay 1538, armature and back contact of relay 1540, winding of relay 1541, lower right-hand contact of relay 1514 60 (4) to battery and ground. Relay 1541 becomes energized and in the manner described prepares a circuit for itself and relay 1540. Upon the next deenergization of the stepping relay 1506, relay 1540 attracts its armature and when relay 1506 energizes, the stepping circuit is extended by way of conductor 1537, armatures and front contacts of relays 1538 and 1540, conductor 1535, thence to conductor 1542, back contact and left-hand armature of relay 1504, winding of relay 1501 to battery and ground. Relay 1501 attracts its armature and prepares a circuit from battery through the winding of said relay, through the windings of relays 1502 and 1503 in parallel, contact and armature of relay 1501, right-hand contacts 1517 to ground. As the commutator brush 718 engages the next metallic segment, relay 1506 deenergizes and relays 1502 and 1503 attract their armatures. Relay 1503 opens the fundamental circuit to prevent further operation of the stepping relay, while relay 1502 closes a circuit from ground, through its armature and contact, contacts 1522, upper right-hand contact 1523 (4), winding of sequence switch magnet 1500 to battery and ground. The sender sequence switch 1500 leaves position 4 and advances into position 6. On passing out of position 6 sequence switch 1500 opens its contacts 1514 and 1517 to permit the release of the energized counting relays.
- 70 As soon after the fundamental circuit is opened by relay 1503 as brush 718 engages an insulating segment of commutator 713, the relay 701 releases its armatures and opens the circuit of the updrive power magnet 709. Relay 709 also completes a circuit from battery through the winding of sequence switch magnet 700, lower right-hand contact 743, back contact and left-hand armature of relay 701 to ground at the left-hand contacts 739. Sequence switch 700 advances from position 8 into position 9.
- 80 With the sequence switch 700 in position 9 and sequence switch 1500 in position 6, the fundamental circuit is again closed in the manner already described for controlling group selection. Relay 701, therefore, energizes and locks up, as explained, over its right-hand winding. Relay 701 also completes a circuit from battery through the winding of sequence switch magnet 700, lower left-hand contact 743 (9), front contact and left-hand armature of relay 701 to ground at the left-hand contacts 739, driving said sequence switch out of position 9 and into position 10. In this position the updrive power magnet 709 is energized in a circuit over the lower contact 742 and front contact and left-hand armature of relay 701. At the same time the trip magnet 712 is energized in a circuit from battery through the winding of said magnet, upper right-hand contact 738 (9+10), upper left-hand

- contact 739 (1+16) to ground. The brush shaft is again elevated and the selected set of brushes are tripped and driven over the terminals with which they cooperate.
- 5 Stepping relay 1506, on energizing in the fundamental circuit, closes a circuit from ground through the upper right-hand contact 1520 (6), armature and contact of relay 1506, lower right-hand contact 1521 (6), upper left-hand contact 1521 (1+12), lower right-hand and upper left-hand contacts 1623, lower right-hand contact 1510 (6), conductor 1341, right-hand armature and front contact of relay 1317, left-hand armature and front contact of relay 1316, outer left-hand armature and front contact of relay 1319, conductor 1315, thence to conductor 1545, Fig. 15, armature and back contact of counting relay 1546, winding of relay 1547, 10 upper left-hand contact 1515 (6) to battery and ground. Relay 1547 attracts its armature and completes a circuit from battery through its winding, the winding of relay 1546 to ground at the contact and armature of relay 1547. Relay 1546, however, being shunted by the stepping relay 1506, does not operate at this time. As the tripped set of brushes of the district switch approach the first group of terminals, commutator brush 15 719 engages a metallic segment of commutator 714 and the following circuit is closed for relay 701 in shunt of the stepping relay 1506: battery, through the right-hand winding and contact and inner right-hand armature of relay 701, lower contact 744, upper left-hand contact 745 (9₄+10), commutator 714, brush 719 to ground. Relay 1506 being shunted, releases its armature and removes the short-circuit from around the winding 20 of counting relay 1546. Relay 1546 thereupon energizes and locks up in series with relay 1547. For each succeeding release of the armature of relay 1506, a pair of counting relays are locked up until finally relays 25 1502 and 1503 are operated. Relay 1503 opens the fundamental circuit and relay 1502 closes a circuit over contacts 1522 and the upper right-hand contact 1523 (6), for driving the sender sequence switch 1500 out of position 6 and into position 8. As the sequence switch 1500 leaves position 6 the energized counting relays are released. In 30 position 8 of sequence switch 1500 a circuit is established from battery through the winding of relays 1501 and 1502 in series, lower left-hand contact 1525 (2+13), upper left-hand contact 1525 (8), to ground at the lower contact 1416 (9+11) of the class sequence switch 1400. Relay 1502 energizes 35 and closes a circuit over contacts 1522 and the upper right-hand contact 1523 (8), for driving the sender sequence switch 1500 into position 10. On leaving position 8 the upper left-hand contact 1525 is opened so that 40 relays 1501 and 1502 becomes deenergized before sequence switch 1500 reaches position 10.
- When the brush 719 encounters an insulating segment of commutator 714, following the opening of the fundamental circuit 45 by relay 1503, the relay 701 retracts its armatures and opens the circuit of the updrive power magnet 709 to position the selected set of brushes 720, 721, and 722, in operative relation to the proper group of terminals in 50 the bank. Relay 701, furthermore, established a circuit from battery through the winding of the sequence switch magnet 700, lower right-hand contact 743 (10), back contact and left-hand armature of relay 701, 55 left-hand contacts 739 to ground, driving sequence switch 700 out of position 10 and into position 11.
- The district sequence switch 700 in position 11 completes a circuit from battery 60 through the right-hand winding of relay 701, lower left-hand contact 745 (11), lower left-hand contact 746 (11+11₄) to ground. Relay 701 attracts its armature and closes a circuit from battery through the winding 65 of sequence switch 700, lower left-hand contact 743 (11), front contact and left-hand armature of relay 701 to ground over the left-hand contacts 739; driving sequence switch 700 out of position 11 and into position 12. Provided the first trunk in the 70 group, upon the terminals of which the brushes 720, 721, and 722 are standing, is busy at this time, a ground potential is present on the test terminal and relay 701 remains energized in the following circuit: 75 battery, through the left-hand winding of said relay, upper right-hand contact 735 (11+12), front contact and outer right-hand armature of relay 701, lower contact 741 80 (11+13), test brush 722 to the grounded test terminal 725. A circuit is therefore closed as follows for the updrive power magnet 709 and the brushes are advanced in the trunk hunting movement: battery, through the 85 winding of magnet 709, lower contact 742 (12), thence over the front contact and left-hand armature of relay 701 to ground, as already described. When the test brush 722 90 encounters the test terminal 725 of the first 95 idle trunk, relay 701 becomes deenergized and opens the circuit of the updrive magnet 709 and also completes a circuit for driving sequence switch 700 out of position 12 and into position 13. This latter circuit may be 100 traced from battery through the winding of said sequence switch, lower right-hand contact 743 (12+13), back contact and left-hand armature of relay 701, lower left-hand contact 739 (1+12), upper left-hand contact 105 739 (1+16) to ground. On reaching position 12₃ sequence switch 700 applies a ground potential to the test terminal 725 of the selected trunk to maintain the same nonselectable to other switches. This potential is 110 115 120 125 130

applied over a circuit from ground through the upper left-hand contact 739 (1+16), lower left hand contact 737 (12 $\frac{3}{4}$ +16 $\frac{1}{4}$), brush 722 to the test terminal 725.

- 5 It will be remembered that the relay 1607
is in its operated condition, having been en-
ergized at the time the district sequence
switch 100 in the originating office reached
position 12. Hence when sequence switch
10 700 arrives in position 13 a circuit is closed
from battery through the winding of relay
703, lower contact 726 (13), conductor 764,
lower right-hand contact 747, conductor 765,
contact and inner right-hand armature of
15 relay 1603, right-hand contacts 1630 (11),
contact and right-hand armature of relay
1607 to ground. Relay 703 operates and
closes a circuit for the energization of re-
lay 705. Relay 705 in turn completes a cir-
20 circuit through its left-hand armature and con-
tact and the winding of the relay 704 to
ground. Relay 704 energizes and closes a
circuit from ground through its left-hand
armature and contact, right-hand contact
25 728 (13+17), winding of relay 702 to bat-
tery and ground. Relay 702 establishes a
circuit from ground through its right-hand
armature and front contact, upper left-hand
contact 734 (13+14), lower left-hand con-
30 tact 734 (13), left-hand armature and back
contact of relay 701, lower right-hand-contact
743 (12+13), winding of, sequence switch
magnet 700 to battery and ground. Se-
quence switch 700 advances into position 14.
35 In this position relay 703 maintains its ener-
gization through a circuit over the upper
contact 126 (13+17), conductor 155, and
thence to ground, as hereinbefore traced,
through the upper right-hand winding of
40 repeating coil 112. As soon as sequence
switch 700 reaches position 14, a circuit is
also established from ground through the
right-hand armature and front contact of
relay 702, upper left-hand contact 734
45 (13+14), lower right-hand contact 734
(14+15), lower right-hand contact 748, con-
ductor 763, contact and inner right-hand ar-
mature of relay 1602, upper right-hand con-
tact 1624 (11+17), lower right-hand con-
50 tact 1622 (1+11), winding of relay 1606 to
battery and ground. Relay 1606 is actuated
and a circuit established from battery
through the winding of sequence switch
magnet 1600, upper left-hand contact 1627
55 (11), front contact and right-hand armature
of relay 1606 to ground through the upper
right-hand contact 1616 (1+11). Sequence
switch 1600 thereupon moves from position
11 into position 12 and relay 1607 becomes
60 deenergized. In position 12 of sequence
switch 1600 a circuit is established from
ground through the lower left-hand contact
1618 (12), conductor 1635, outer left-hand
armature and contact of relay 1603, conduc-
65 tor 766, lower right-hand contact 749, upper

right-hand and lower left-hand contacts 736 (3+16), lower right-hand contact 735 (14), left-hand winding of relay 701 to battery and ground. Relay 701 is operated and establishes a circuit from battery through the 70 winding of sequence switch magnet 700 lower left-hand contact 743 (14), front contact and left-hand armature of relay 701, lower left-hand contact 739 (14), upper left-hand contact 739 (1+16) to ground, driving 75 said sequence switch out of position 14 and into position 15.

Operation of the office switch.

The fundamental circuit for controlling brush selection of the office switch 850 is now established from battery through the right-hand winding of relay 801, lower left-hand contact 814 (1), left-hand contact 805 (1+4), conductor 831, terminal 723, brush 720, lower right-hand contact 756 (1+16), lower left-hand contact 756 (13+15), lower right-hand contact 751, conductor 769, contact and inner right-hand armature of relay 1604, lower right-hand contact 1633 (5+17), lower left-hand contact 1633, (5+12), right-hand contacts 509 (10+12), winding of stepping relay 1506, armature and contact of relay 1503, upper contact 1527 (10), lower right-hand contact 1526 (10), lower left-hand contact 1526 (10+12), left-hand contact 1413 (9+11), conductor 1549, lower right-hand contact 1631 (5+12), upper left-hand contact 1629 (5+14), contact and outer left-hand armature of relay 1608, conductor 1636, outer right-hand armature and contact of relay 1604, conductor 767, lower right-hand contact 755, lower left-hand contact 757 (13+15), lower right-hand contact 757 (1+16), brush 721, terminal 724, upper right-hand contact 807 (1+4), lower left-hand contact 807 (7+5), to ground. Relay 801 is actuated and is locked up in a circuit from battery through its right-hand winding and front contact and right-hand armature and lower right-hand contact 814 (1+4), thence over the fundamental circuit, as described. Relay 801 closes a circuit from ground through its left-hand armature and front contact, lower left-hand contact 809 (1), winding of sequence switch magnet 800 to battery and ground, driving said sequence switch out of position 1 and into position 2. In this position a circuit is established from battery through the winding of the updrive power magnet 802, lower contacts 810 (2) to ground at the front contact and left-hand armature of relay 801. Magnet 802 causes the upward movement of the brush shaft in the well-known manner.

When the stepping relay 1506 first energizes in the fundamental circuit it established a circuit from ground through the lower right-hand contact 1520 (10), contact and armature of relay 1506, upper right-hand

contact 1521 (10), upper left-hand contact 1521 (1+12), lower right-hand and upper left-hand contact 1623, right-hand contact 1511 (10), conductor 1342, right-hand armature and front contact of register relay 1327, left-hand armature and back contact of relay 1328, inner left-hand armature and front contact of relay 1326, contact 1408 (9+3) of sequence switch 1400, conductor 1407, 5 thence to conductor 1550, Fig. 15, armature and back contact of counting relay 1551, winding of relay 1552, upper right-hand contact 1515 (10) to battery and ground. Relay 1552 energizes and in the well-known 10 manner prepares a locking circuit for itself and relay 1551. For each brush tripping position assumed by the office switch 850 in its upward movement, a circuit is closed as follows for shunting the stepping relay 20 1506 in the fundamental circuit: battery, through the right-hand winding and front contact and right-hand armature of relay 801, lower right-hand contact 814 (1+4), upper right-hand contact 814 (1₄+2), commutator 815, brush 818 to ground. Each 25 time the stepping relay 1506 is shunted an additional pair of counting relays are energized and locked up until finally the 0 counting relays 1501, 1502, and 1503 are operated. 30 Relay 1503 serves to open the fundamental circuit and relay 1502, at its armature and contact, completes a circuit over the contacts 1522 and the upper right-hand contact 1523 (10), for driving the sender sequence switch 1500 out of position 10 and 35 into position 12.

After the fundamental circuit is opened by relay 1503 and the commutator brush 818 engages the next insulating segment of commutator 815, relay 801 releases its armature and opens the circuit of the updrive magnet 802. Relay 801, furthermore, closes a circuit from ground through its left-hand armature and back contact and the upper 45 left-hand contact 809 (2), for driving sequence switch 800 into position 3. In this position a circuit is established from battery through the winding of trip magnet 804, upper right-hand contact 811 (3+7) to 50 ground. Magnet 804 operates the trip spindle preparatory to tripping the selected set of brushes on the next upward movement of the brush shaft.

The fundamental circuit is closed once 55 more in positions 3 and 12 of sequence switches 800 and 815 respectively and relays 801 and 1506 are actuated. Relay 801, at its left-hand armature and front contact closes a circuit including the lower left-hand 60 contact 809 (3), for driving sequence switch 800 into position 4. Relay 801 remains locked up in position 4 over its right-hand winding. The updrive power magnet is also energized in this position over the circuit above traced including the lower con-

tacts 810. The brush shaft is elevated and the tripped set of brushes driven over the terminals of the bank in the group selecting movement.

The stepping relay 1506, on energizing, 70 establishes a circuit from ground through the upper right-hand contact 1520 (12), armature and contact of relay 1506, lower right-hand contact 1521 (12), upper left-hand contact 1521 (1+12), lower right-hand 75 and upper left-hand contacts 1623, left-hand contact 1511 (12), conductor 1343, right-hand armature and front contact of register relay 1323, left-hand armature and front contact of relay 1324, outer left-hand armature 80 and front contact of relay 1322, conductor 1320, thence to conductor 1545, Fig. 15, armature and back contact of counting relay 1546, winding of relay 1547 to battery and ground. Relay 1547 operates and prepares 85 a series holding circuit for itself and the relay 1546. For each group of terminals approached by the tripped set of brushes 822, 823, and 824, brush 820 engages a metallic segment of commutator 816 to close as 90 follows a shunt circuit around the winding of the stepping relay 1506: battery, through the right-hand winding and front contact and right-hand armature of relay 801, lower right-hand contact 814 (1+4), upper left-hand contact 814 (3₄+4), commutator 816, brush 820 to ground. For each deenergization of stepping relay 1506, a pair of counting relays are energized until finally the No. 1' counting relay 1540 is operated. It will 100 be recalled that at the time the relay registers were being positioned by the impulse machine that relay 1311 was also energized and locked up. The purpose of this relay is to distinguish between selections involving digits greater or less than five. Since the stepping circuit controlled by the stepping relay 1506 can only be extended through the contacts of the relay registers to five different counting relays, it becomes 105 necessary where the selection involves a digit greater than five to provide for the operation of more than five pairs of counting relays. Therefore, as in the case assumed where the brushes of the office switch must 110 traverse more than five groups of terminals to reach the desired one, relay 1311 is operated. When the sender sequence switch passes into position 12, a circuit is closed from battery through the winding of the 120 translation relay 1504, upper contact 1519 (5+12), lower left-hand contact 1519 (11+12), conductor 1344, contact and outer armature of relay 1311, conductor 1345, lower left-hand contact 1620 (5+12) to ground. 125 Since then, relay 1504 is operated at the time the No. 1' counting relay 1540 attracts its armature, the stepping circuit is now extended by way of conductor 1535, thence to conductor 1542, right-hand armature and 130

contact of relay 1504, armature and back contact of No. 9' relay 1564, winding of the No. 9 relay 1565, lower right-hand contact 1515 (12) to battery and ground. Relay 5 1565 energizes and prepares a circuit, as explained for the relay 1564. The switch 850, therefore, continues its upward movement and for each group of terminals traversed a succeeding pair of counting relays in the 10 lower group are operated and locked up. When at last the No. 5' counting relay 1553 attracts its armature, the stepping circuit is extended by way of conductor 1554, front contact and left-hand armature of relay 15 1504, winding of relay 1501 to battery and ground. On the next deenergization of the stepping relay 1506, relays 1502 and 1503 are 20 actuated to open the fundamental circuit and also to drive the sender sequence switch 1500 out of position 12 and into position 13. Immediately following the opening of the fundamental circuit at the sender, brush 820 encounters an insulating segment of the 25 commutator 816 and relay 801 releases its armatures to open the circuit of the updrive power magnet 802. Relay 801 also closes a circuit over its left-hand armature and back contact and upper left-hand contact 809, for driving sequence switch 800 out of position 30 4 and into position 5.

In position 5 of sequence switch 800, relay 801 is energized in the circuit from battery through its left-hand winding, lower contacts 812, closed in position 5, to ground. Relay 801, at its left-hand armature and front contact, closes a circuit for driving sequence switch 800 out of position 5 and into position 6. Provided the first trunk in the 35 group of trunks leading to the terminating office, upon the terminals of which the brushes 822, 823, and 824 are now standing, is busy, a ground potential exists on the test terminal 827 and relay 801 is maintained energized in the following circuit: battery, through the right-hand winding and front contact and right-hand armature of 40 said relay, upper left-hand contact 813 (5+18), lower right-hand contact 813 (5+84), brush 824, terminal 827 to ground.

The maintained energization of relay 801 causes the upward movement of the brush shaft in the trunk hunting operation. The 45 circuit for the updrive power magnet 802 is the same as the one hereinbefore traced over the lower contacts 810. When the first idle trunk in the group is reached, relay 801 becomes deenergized and opens the circuit of the updrive power magnet 802, and closes a circuit from ground over its left-hand armature and back contact for driving sequence switch 800 out of position 6 and into position 7. In position 7, relay 801 immediately energizes by means of a circuit 50 through its left-hand winding and lower contacts 812 to ground. Relay 801, at its 55 left-hand armature and front contact, completes a circuit over the lower left-hand contact 809 (7), for driving the sequence switch into position 8. Relay 801 remains energized in position 8 in a circuit from battery through its right-hand winding, front contact and right-hand armature, upper left-hand contact 813 (5+18), lower left-hand contact 813 (63+18), conductor 828, terminal 70 725, brush 722, lower left-hand contact 737 (124+164), upper left-hand contact 739 to ground. The connection is thus extended over the interoffice trunk conductors 829 and 830 to the incoming switch at the terminating office.

As the sender sequence switch 1500 advances into position 13, following the completion of the office group selection, the following circuit is established for moving the controlling sequence switch 1600 out of position 80 13: battery, through the winding of sequence switch magnet 1600, upper left-hand contact 1619 (12), conductor 1149, upper contact 1181 of register 1180, conductor 1139, back contact and right-hand armature 90 of relay 1606, conductor 1637, lower right-hand contact 1516 (13), upper right-hand contact 1517 (2+18) to ground. Sequence switch 1600, on leaving position 12, opens its lower left-hand contact 1620 to permit 95 the deenergization of the translation relay 1504. Moreover, a circuit is established in this position to move the sender sequence switch 1500 out of position 13 and into position 14. This circuit may be traced from 100 battery through the winding of said sequence switch, upper right-hand contact 1524, lower right-hand contact 1620 (13+14) to ground.

Operation of incoming and final selector switches. 105

As soon as the interoffice trunk circuit 829, 830 has been selected by the office switch 850, the sender makes a test to determine 110 that the sequence switch 900 of the incoming selector switch is in its normal position. The circuit for performing this test may be traced from battery through the lower right-hand contact 928 (1+2), left-hand winding of relay 901, lower left-hand contact 923 (1+3), lower right-hand contact 923 (1), conductor 951, lower left-hand contact 918 (1+4), left-hand contact 918 (1+4), left-hand contact 916 115 (1+8), conductor 829, terminal 825, brush 822, contacts 805 (8), conductor 831, terminals 723, brush 720, lower contacts 756, lower right-hand contact 751, conductor 769, contact and inner right-hand armature of 120 relay 1604, lower right-hand contact 1633 (5+17), upper right-hand contact 1634 (13), conductor 1555, upper left-hand contact 1529 (14+16), upper right-hand contact 1529 (14+144), winding of relay 1507, 130

resistance 1532, upper right-hand contact 1530 (14+16), resistance 1531, upper contact 1533 (14+14 $\frac{1}{4}$), conductor 1556, lower right-hand contact 1629 (13), upper left-hand contact 1629 (5+14), contact and outer left-hand armature of relay 1608, outer right-hand armature and contact of relay 1604, conductor 767, lower right-hand contact 755, lower contacts 757, brush 721, 5 terminal 724, conductor 832, contact 806 (8), brush 823, terminal 826, conductor 830, left-hand contacts 917 (1+8), to ground. Relay 1507, at the sender, becomes energized in this circuit, but due to the resistances 1531 and 1532, relay 901, at the incoming selector switch, does not receive sufficient current to operate. Relay 1507, at its left-hand armature and contact, closes a circuit for the energization of relay 1508. Relay 1508 completes a circuit from ground through the inner left-hand armature and contact, conductor 1548, right-hand contact 1412 (10), lower right-hand contact 1524 (14+18), winding of sequence switch 1500 to battery 20 and ground. The sequence switch 1500 leaves position 14. On reaching position 14 $\frac{1}{4}$, the resistance 1532, included in the above traced circuit, is removed, said test circuit being traceable over conductor 1555, upper left-hand contact 1529 (14+16), lower right-hand contact 1529 (14+16), contact and outer left-hand armature of relay 1508, winding of relay 1507, lower left-hand contact 1530 (14 $\frac{1}{4}$ +16), upper right-hand contact 1530 (14+16), resistance 1531, right-hand contact 1414 (10), contact and right-hand armature of relay 1508, lower contact 1533 (14+16), conductor 1556, and thence to ground at the incoming selector switch as above traced. The removal of resistance 1532 has no effect in the test circuit at this time since the remaining resistance 1531 is high enough to prevent the flow of sufficient current to operate the relay 901. As sequence switch 1500 leaves position 16, the first circuit is opened and relays 1507 and 1508 release their armatures. On reaching position 17, the sequence switch 1500 is now driven into position 2 by means of the following circuit: battery, through the winding of said sequence switch, upper right-hand contact 1524 (17+1), lower right-hand contact 1620 (13+14), to ground. The controlling sequence switch 1600 is now advanced into position 14 by means of a circuit from battery through the winding of said sequence switch, upper right-hand contact 1619 (13), upper left-hand contact 1516 (2), upper right-hand contact 1517 (2+18) to ground. 55 With the sender sequence switch 1500 in position 2, the fundamental circuit is established for making the selection of a set of brushes at the incoming selector switch 950. This circuit is traceable from battery 60 through the lower right-hand contact 928 (1+2), left-hand winding of relay 901, lower contacts 923, lower left-hand contact 918 (1+4), right-hand contact 916 (1+8), thence, as above traced, over conductor 829 to conductor 769, contact and inner right-hand armature of relay 1604, lower right-hand contact 1633, lower left-hand contact 1633 (14), right-hand contacts 1509 (2+6), winding of stepping relay 1506, armature 75 and contact of relay 1503, upper right-hand contact 1529 (2), left-hand winding of relay 1505, contact 1415 (10), conductor 1557, upper right-hand contact 1629 (14), upper left-hand contact 1629 (5+14), contact and outer left-hand armature of relay 1608, outer right-hand armature and contact of relay 1604, conductor 767, thence, as above traced, to conductor 830, left-hand contacts 917 to ground. Relays 901 and 80 1506 become energized in the fundamental circuit by relay 1505, being polarized and differential, does not operate when current of this polarity is flowing through its left-hand winding. The right-hand winding of relay 1505 is energized in a circuit closed at the lower left-hand contact and upper right-hand contact 1517 (2+18). The flux produced by the right-hand winding of said relay is insufficient to attract its armature. 95 The relay becomes active only when current of a polarity flows through the left-hand winding such that the flux produced thereby is cumulative with respect to the flux produced by the right-hand winding. The 100 purpose of this relay will be discussed later on.

The operation of relay 901, at the terminating office, results in the closure of a circuit from battery, through the winding of sequence switch magnet 900, upper left-hand contact 927 (1), front contact and outer armature of relay 901 to ground. Sequence switch 900 advances from position 1 into position 2 and relay 901 remains locked up 105 in a circuit from battery over the lower right-hand contact 928, left-hand winding and front contact and inner armature of relay 901, lower left-hand contact 918 (1+4), and thence over the fundamental circuit, as 110 already traced. The updrive power magnet 904 of the switch 950 is now energized and the brush shaft is elevated in the brush selecting operation. The circuit for magnet 904 may be followed from battery through 115 the winding of said magnet, upper right-hand contact 927 (2), to ground at the front contact and outer armature of relay 901. The stepping relay 1506, which also energizes in the fundamental circuit, closes a circuit from ground through the upper right-hand contact 1520, armature and contact of relay 1506, lower right-hand contact 1521 (2), upper left-hand contact 1521 (1+12), lower right-hand contact 1623 (5+14), 120 125 130

lower left-hand contact 1623 (14), upper right-hand contact 1512 (2+6), lower right-hand contact 1512 (2), conductor 1558, upper contact 1135 of register 1130, conductor 5 1177, thence to conductor 1537, Fig. 15, armature and back contact of the No. 2' counting relay 1538, winding of No. 2 counting relay 1539 to battery and ground. Relay 1539 operates and prepares a circuit for 10 relay 1538. As the selector switch 950 approaches each brush tripping position, brush 936 engages the metallic segment of commutator 938 and a circuit is closed as follows in shunt of the winding of the stepping relay 15 15 1506: battery, through the left-hand winding of relay 901, front contact and inner armature of said relay, lower left-hand contact 918 (1+4), upper left-hand contact 918 (1 $\frac{1}{4}$ +2), commutator 938, brush 936, left- 20 hand contact 930 (7+5) to ground. Each time the stepping relay 1506 deenergizes, a pair of counting relays are energized and locked up until finally the relays 1501, 1502, and 1503 operate. Relay 1503 opens the 25 fundamental circuit and relay 1502 closes a circuit over contacts 1522 and upper right-hand contact 1523, for advancing sequence switch 1500 out of position 2 and into position 4. As soon after the fundamental circuit 30 is opened at the sender as brush 936 encounters an insulating segment of commutator 938, relay 901 releases its armatures and opens the circuit of the updrive power magnet 904. Relay 901 also closes a circuit from ground 35 over its left-hand armature and back contact and the lower left-hand contact 926 (2), for driving sequence switch 900 into position 3. In this position the trip magnet 906 is energized in a circuit closed over the lower 40 right-hand and upper left-hand contacts 932, preparatory to tripping the selected set of brushes on the next upward movement of the brush shaft. The fundamental circuit is again closed over the above traced path and 45 relays 901 and 1506 become energized. Relay 901 locks up, as above described, and closes a circuit from ground over its outer left-hand armature and front contact, for driving sequence switch 900 out of position 50 3 and into position 4. In position 4 of sequence switch 900, the updrive power magnet is energized in the circuit traced over the upper right-hand contact 927, and the brush shaft is elevated in the group selecting 55 movement.

At the sender the stepping relay 1506 energizes and completes a circuit from ground over the lower right-hand contact 1520 (4), contact and armature of relay 1506, upper 60 contacts 1521, lower contacts 1623, upper right-hand contact 1512 (2+6), upper left-hand contacts 1512 (4), conductor 1559, upper contact 1145 of register 1140, conductor 1119, thence to conductor 1536, Fig. 15, 65 armature and back contact of relay 1540, winding of relay 1541 to battery and ground. Relay 1541 attracts its armature and prepares a circuit for relay 1540. As the brushes 942, and 943, and 944 of the incoming selector switch are advanced into operative relation with each successive group of terminals in the bank, a circuit is closed as follows for shunting out the stepping relay 1506 in the fundamental circuit: battery, lower left-hand contact 928, left-hand winding and 70 front contact and inner armature of relay 901, lower left-hand contact 918 (1+4), upper right-hand contact 918 (3 $\frac{1}{4}$ +4), commutator 940, brush 935 to ground at the left-hand contact 930. For each deenergization 75 of relay 1506, a pair of counting relays are operated and when finally relays 1502 and 1503 attract their armatures, the fundamental circuit is opened and the sender sequence switch 1500 is advanced from position 4 to 80 position 6. Following the opening of the fundamental circuit at the sender, the brush 935 engages an insulating segment of commutator 940, the circuit of relay 901 is opened 85 and this relay releases its armatures to open 90 the circuit of the updrive magnet 904. Relay 901 also completes a circuit over its outer armature and back contact for advancing sequence switch 900 out of position 4 and into 95 position 5.

In position 5 of sequence switch 900 a circuit is completed from battery through the lower left-hand contact 928, right-hand winding of relay 901, upper left-hand and lower right-hand contacts 931 to ground. Relay 901 becomes energized and closes a circuit from ground through its outer armature and front contact and the upper left-hand contact 927 (5), for moving sequence switch 900 into position 6. When leaving 100 position 5 $\frac{1}{4}$ sequence switch 900 opens, at the lower right-hand contact 931, the circuit for the right-hand winding of relay 901. Relay 901, however, is held energized provided the first trunk in the group, upon which the 105 brushes 942, 943, and 944 are standing, is busy. The holding circuit may be traced from battery through the lower left-hand contact 928, left-hand winding and front contact and inner armature of relay 901, lower left-hand contact 932 (5+7), upper right-hand contact 932 (5+15), brush 944 to the grounded test terminal 947. In position 6 the updrive power magnet 904 is again 110 energized over the above traced circuit and the brushes are driven over the selected group of trunks to search for an idle one thereof. When the first idle trunk is reached, relay 901 becomes deenergized, opens the circuit of the power magnet 904, and completes 115 a circuit over its outer armature and back contact and the lower left-hand contact 926 (6), for advancing sequence switch 900 into position 7. In position 7 relay 901 is operated in a circuit from battery through the 120 125 130

lower left-hand contact 928, left-hand winding of relay 901, left-hand contacts 923, (7) 5 lower contact 934 (7+8), brush 943, terminal 946, conductor 953, upper left-hand contact 1009 (17+15), lower right-hand contact 1009 (1+8½), lower left-hand contact 1019 (1+8½) to ground. Relay 901 closes a circuit over its outer left-hand armature and front contact and upper left-hand contact 10 927, for advancing sequence switch 900 into position 8. Relay 901 remains energized in a circuit through its left-hand winding and front contact and inner armature, lower right-hand contact 923 (7½+8), upper left- 15 hand contact 923 (7+11), thence to ground, as described, since the lower right-hand contact 923 is closed in position 7½, just prior to the opening of the lower left-hand contact 923, as the sequence switch moves into position 20 8.

The fundamental circuit is closed once more for controlling the brush selecting operation of the final switch 1050. This circuit may be traced from battery through the 25 left-hand contact 1020 (1+10), right-hand winding of relay 1001, lower left-hand contact 1010 (1), lower left-hand contact 1008 (15+6), conductor 952, terminal 945, brush 942, lower right-hand contact 918 (8), left- 30 hand contact 916 (1+8), conductor 829, thence over the circuit hereinbefore traced to the conductor 769, contact and inner right-hand armature of relay 1604, lower contacts 1633, right-hand contacts 1509, 35 winding of stepping relay 1506, armature and contact of relay 1503, upper right-hand contact 1529 (6), left-hand winding of relay 1505, contact 1415 (10), conductor 1557, upper right-hand contact 1629 (14), upper left- 40 hand contact 1629 (5+14), outer left-hand armature and contact of relay 1608, conductor 1636, and thence over the other side of the circuit already traced to conductor 830, left-hand contacts 917 to ground. Relay 1001 45 attracts its armatures and completes a circuit from battery through the left-hand winding of relay 1002, conductor 1037, upper left-hand contact 1017 (1), front contact and left-hand armature of relay 1001, upper 50 left-hand contact 1014 (1+11) to ground. Relay 1002 is energized and a circuit is closed from ground through the right-hand armature and front contact of said relay, lower left-hand contact 1013 (1), lower 55 right-hand contact 1013 (1+13), winding of sequence switch magnet 1000 to battery and ground. Sequence switch 1000 thereupon advances from position 1 into position 2, and the relay 1001 remains energized in a circuit 60 through its right-hand winding, lower right-hand contact 1016 (15+10), front contact and right-hand armature of relay 1001, lower right-hand contact 1010 (1+6), and thence to ground over the fundamental 65 circuit as explained. A circuit is now closed

for the high speed updrive power magnet 1005 and the brush shaft is elevated in the brush selecting movement. This circuit may be followed from battery through the winding of said magnet, upper right-hand contact 1018 (2), front contact and left-hand armature of relay 1001, upper left-hand contact 1014 (1+11) to ground. Relay 1002, which energized in position 1 of sequence switch 1000, maintains its operation in a 70 circuit from battery through the left-hand winding of said relay, armature and contact of relay 1003, front contact and left-hand armature of relay 1002, conductor 955, terminal 947, brush 944, upper right-hand contact 932 (5+15½), upper left-hand contact 932 (6½+18) to ground.

The stepping relay 1506, which also energizes in the fundamental circuit, closes a circuit from ground through the upper 85 right-hand contact 1520, armature and contact of relay 1506, lower right-hand and upper left-hand contact 1521, lower contacts 1623, upper right-hand contact 1512 (2+6), lower left-hand contact 1512 (6), conductor 90 1560, lower contact 1155 (2), of register 1150, conductor 1177, thence to conductor 1537, Fig. 15, armature and back contact of relay 1538, winding of relay 1539 to battery and ground over the lower left-hand contact 95 1514. Relay 1539 operates and prepares a holding circuit for itself in series with relay 1538. As the switch 1050 approaches each brush tripping position, a circuit is closed as follows for shunting out the stepping relay 1506 in the fundamental circuit: battery, through the left-hand contact 1020, right-hand winding of relay 1001, lower right-hand contact 1016 (15+10), front contact and right-hand armature of relay 1001, 105 lower right-hand contact 1010 (1+6), upper right-hand contact 1008 (1+2), commutator 1026, brush 1024, upper left-hand contact 1019 (13+11), to ground. Each time the stepping relay 1506 is shunted out, 110 a pair of counting relays are energized and locked up until finally the 0 counting relays 1501, 1502, and 1503, are operated. Relay 1503 opens the fundamental circuit and relay 1502 closes a circuit over contacts 1522 115 and the upper right-hand contact 1523 (6), for advancing the sender sequence switch 1500 out of position 6 and into position 8. The sequence switch 1500 immediately advances from position 8 into position 10 by 120 means of a circuit from battery through the winding of the magnet of said sequence switch, upper right-hand contact 1524 (8), lower right-hand contact 1620 (13+14), to ground. Following the opening of the fundamental circuit at the sender, the brush 1023 encounters an insulating segment of commutator 1026 and relay 1001 becomes deenergized. Relay 1001 opens the circuit 125 of the power magnet 1005 and completes a 130

circuit from ground through the upper left-hand contact 1014, left-hand armature and back contact of relay 1001, upper right-hand contact 1015 (2), winding of sequence switch magnet 1000 to battery and ground. 5 This sequence switch thereupon advances from position 2 to position 3.

With sequence switch 1000 in position 3 the fundamental circuit is closed in the 10 manner already described for controlling tens selection and relays 1001 and 1506 become energized. Relay 1001 closes a circuit from ground through its left-hand armature and front contact and the lower right-hand 15 contact 1015 (3), for driving sequence switch 1000 out of position 3 and into position 4. In the manner already described, relay 1001 remains locked up in position 4 of sequence switch 1000 in a circuit closed 20 through the front contact and right-hand armature of said relay. The high speed up-drive power magnet 1005 is again energized in the circuit above described and the brush shaft is elevated to select the proper group 25 of ten terminals. On the first upward movement of the brush shaft in the tens selecting operation, the trip magnet 1007, which is now energized, causes the tripping of the selected set of brushes 1029, 1030, and 30 1031. Magnet 1007 is energized in a circuit closed through the lower right-hand contact 1019 (3+5). For each group of ten terminals approached by the brushes 1029, 1030, and 1031, a circuit is closed as follows for 35 shunting the stepping relay 1506: battery through the left-hand contact 1020, right-hand winding of relay 1001, lower right-hand contact 1016 (15+10), front contact and right-hand armature of relay 1001, lower 40 left-hand contact 1010 (1+6), upper right-hand contact 1010 (3+4), commutator 1027, brush 1023 to ground through the upper left-hand contact 1019 (13+11).

The stepping relay 1506, on energizing, 45 closes a circuit from ground through the lower right-hand contact 1520 (10), contact and armature of said relay, upper contacts 1521, lower contacts 1623, upper right-hand contact 1512 (10+18), upper left-hand contact 1513 (10), conductor 1561, upper left-hand contact 1165 (5) of register 1160, conductor 1178, and thence to conductor 1542, Fig. 15, right-hand armature and contact of relay 1504, armature and back contact of 55 relay 1564, winding of relay 1565, lower right-hand contact 1515 (10) to battery and ground. It will be observed that since the tens register 1160 is standing in position 5, a position which represents a digit greater 60 than 4, the contact 1179 thereof is closed, hence the translation relay 1504 is energized at this time in a circuit from battery through the winding of said relay, upper right-hand contact 1519 (5+12), lower left-hand contact 1518 (9+10), conductor 1562,

contact 1179 to ground at the upper left-hand contact 1620 (14). Therefore, the No. 9 counting relay 1565 is energized in the circuit above traced and prepares a series circuit for itself and relay 1564. Each time 70 the stepping relay 1506 is deenergized as the brush shaft advances from one group to another, a pair of counting relays are energized and locked up until finally the relay 1553 is operated. The stepping circuit is 75 now extended over the armature and front contact of relay 1553, front contact and left-hand armature of the translation relay 1504, winding of relay 1501 to battery and ground. Relay 1501 becomes energized and 80 later when relays 1502 and 1503 are operated, the fundamental circuit is opened and the sender sequence switch 1500 advanced out of position 10 and into position 12. When sequence switch 1500 leaves position 85 10, the energized counting relays are released and also the translation relay 1504. After the fundamental circuit has been opened and the brush 1023 reaches the next insulating segment of commutator 1027, relay 1001 releases its armatures, opens the circuit of the updrive magnet 1005, and closes a circuit from ground through the upper left-hand contact 1014 (1+11), left-hand armature and back contact of relay 90 1001, and upper right-hand contact 1015 (4), for driving sequence switch 1000 out of position 4 and into position 5.

The fundamental circuit is now closed for the last time to control the final selector 100 switch in its unit selecting operation. Relays 1001 and 1506 are energized in the manner well understood and a circuit is closed through the left-hand armature and front contact of relay 1001, and the lower right-hand contact 1015 (5), for advancing sequence switch 1000 to position 6. In this position a circuit is established from battery through the winding of the low speed updrive magnet 1004, lower left-hand contact 1017 (6), front contact and left-hand armature of relay 1001, upper left-hand contact 1014 (1+11) to ground. The switch is operated under the control of magnet 1004 at a lower speed to select the desired set of 115 terminals. Each time a set of terminals is passed over by brushes 1029, 1030, and 1031, the circuit through the right-hand winding of relay 1001 is extended to ground in shunt of the stepping relay 1506 over the lower 120 right-hand contact 1010 (1+6), upper right-hand contact 1008 (5+6), commutator 1026, and brush 1024.

The stepping relay 1506, on energizing in the fundamental circuit, closes a circuit from ground through the upper right-hand contact 1520, armature and contact of relay 1506, lower right-hand contact 1521 (12), upper left-hand contact 1521 (1+12), lower contacts 1623, upper right-hand contact 130

- 1512 (2+6), upper right-hand contact 1513 (12), conductor 1563, lower contact 1175 to register 1170, conductor 1177, thence to conductor 1537, Fig. 15, armature and back 5 contact of relay 1538, winding of relay 1539, lower left-hand contact 1514 (12) to battery and ground. Relay 1539 operates and closes a circuit for itself in series with relay 1538. Each time the stepping relay 10 1506 is shunted out by the commutator brush 1024, a pair of counting relays are energized and locked up, and when finally the relays 1502 and 1503 are operated, the fundamental circuit is opened and the sender 15 sequence switch 1500 is driven from position 12 into position 13. From this position the sequence switch 1500 is immediately moved into position 14 by means of a circuit from battery through the winding 20 of said sequence switch, upper right-hand contact 1524 (13), lower left-hand contact 1524 (13), lower left-hand contact 1620 (13+14) to ground. After the fundamental circuit has been opened at the sender and 25 brush 1024 engages an insulating segment of commutator 1026, relay 1001 releases its armatures and opens the circuit of the up-drive power magnet 1004. The switch comes to rest with brushes 1029, 1030, and 30 1031 in engagement with the terminals 1032, 1033, and 1034 of the called line. Relay 1001 also closes a circuit from ground through the upper left-hand contact 1014 (1+11), left-hand armature and back contact 35 of said relay, upper right-hand contact 1015 (6), through the winding of sequence switch magnet 1000 to battery and ground. Sequence switch 1000 leaves position 6 and advances into position 9.
- 40 It will first be assumed that the called line is idle. As sequence switch 1000 reaches position $8\frac{3}{4}$, a circuit is closed from battery through the left-hand contact 1020 (1+10), right-hand winding of relay 1001, lower 45 right-hand contact 1016 (15+10), upper left-hand contact 1016 (8 $\frac{3}{4}$ +9), front contact and right-hand armature of relay 1002 to ground. Relay 1001 becomes energized and when sequence switch 1000 arrives in 50 position 9 a circuit is closed from battery through the winding of said sequence switch, lower right-hand contact 1015 (9), front contact and left-hand armature of relay 1001 to ground at the upper left-hand contact 1014 (1+11). Sequence switch 1000 leaves position 55 9 and advances in position 12. When sequence switch 1000 leaves position 9, the circuit for the right-hand winding of relay 1001 is opened at the upper left-hand contact 1016, but this relay remains energized in 60 a circuit from battery through the left-hand contact 1020 (1+10), right-hand winding of relay 1001, lower right-hand contact 1016 (15+10), front contact and right-hand armature of relay 1001, upper right-hand contact 65 1021 (1+15), upper left-hand contact 1021 (9+10). When sequence switch 1000 leaves position 10, the circuit just traced for the right-hand winding of relay 1001 is also opened, but this relay now remains energized 70 in a circuit from battery through the left-hand winding thereof, lower right-hand contact 1012 (10+11), front contact and left-hand armature of relay 1001 to ground at the upper left-hand contact 1014 (1+11). 75 In position 12 of sequence switch 1000, this circuit is opened and relay 1001, deenergizing, establishes a circuit from battery through the winding of sequence switch magnet 1000, upper right-hand contact 1014 (12), back contact and left-hand armature of relay 1001, lower left-hand contact 1014 (12) to ground at the front contact and right-hand armature of relay 1002. Sequence switch 1000 advances from position 80 12 into position 13, where a circuit is closed from battery through the winding of said sequence switch, lower right-hand contact 1013 (1+13), lower left-hand contact 1013 (13), front contact and right-hand armature of 85 relay 1002 to ground. Sequence switch 1000 thereupon moves into position 14 and a circuit is completed from battery through the winding of said sequence switch, upper right-hand contact 1015 (14), back contact 90 and left-hand armature of relay 1001, upper left-hand contact 1014 (12 $\frac{3}{4}$ +16) to ground. Sequence switch 1000 moves into position 15, which is the talking position. Before proceeding with an explanation of 95 the manner in which the sequence switch 900 at the incoming selector switch is advanced for the purpose of applying ringing current to the called line, the release of the register sending mechanism in the tandem office will 100 be considered.
- Release of sender and restoration
of registers.*
- At the time the sender sequence switch 10 1500 reaches position 14, a circuit is established as follows for advancing the district selector sequence switch 700 out of position 15 and into the talking position 16: battery, 15 through the winding of the magnet of said sequence switch, lower right-hand contact 743 (15), back contact and left-hand armature of relay 701, lower left-hand contact 734 (15), lower right-hand contact 734 (14+15), lower right-hand contact 748 (1), conductor 763, contact and inner right-hand armature of relay 1602, upper right-hand contact 1624 (11+17) left-hand contact 1624 (14), upper right-hand contact 1516 (14), upper right-hand contact 1517 (2+18) to ground. When sequence switch 700 leaves position 15, it opens, at its lower right-hand contact 738, the circuit which up to this time has been maintaining the energization of relay 1602. Relay 1602, there- 125 130

- fore, releases and opens the holding circuit of relays 1603 and 1604. Over its back contact and left-hand armature, lower contact 1621 (2+18) and conductor 762, the relay 1602 places a ground potential on the multiples of sender selector sequence switch contact 753 to maintain this sender busy until sequence switch 1600 has passed out of position 18. The relay 1603, on deenergizing, 5 closes a circuit from battery through the winding of sequence switch magnet 1600, upper right-hand contact 1627 (2+17), back contact and outer left-hand armature of relay 1604 to ground, driving said sequence switch out of position 14 and into position 18. In position 18 of sequence switch 1600, a circuit is completed from battery through the winding of sequence switch magnet 1500, upper left-hand contact 1524 (2+16), 10 lower left-hand contact 1628 (18) to ground. The sender sequence switch 1500 is energized in this circuit and moves out of position 14 and into position 17. Provided the translator switch 1260 has been re- 15 stored to normal at this time and the register 1100 is in position 1, the sender sequence switch 1500 is advanced into position 18 by means of a circuit from battery through the winding of said sequence switch, upper 20 left-hand contact 1523 (17), conductor 1265, upper right-hand contact 1206 (1), contact and inner right-hand armature of relay 1202, conductor 1262, lower left-hand contact 1107 (1) to ground. From 25 here the sequence switch 1500 is immediately driven into position 1 by means of a circuit closed through the left-hand contacts 1528 (18).

As the controlling sequence switch 1600 moves out of position 14, the upper right-hand contact 1620 is opened and relay 1610 releases its armatures. The release of the armatures of this relay removes ground potential from conductors 1331, 1332, 1333, 45 and 1336, and all energized register relays and class relays in Figs. 13 and 14 respectively are released.

In position 18 of the controlling sequence switch 1600, the following circuits are closed 50 for restoring the registers 1110, 1120, 1130, etc., battery, through the winding of register 1110, upper right-hand contact 1114 (0+16), lower left-hand contact 1617 (18) to ground, battery, through the winding of register 1120, upper right-hand contact 1124 (0+16), lower right-hand contact 1617 (18) to ground; battery, through the winding of register 1130, upper right-hand contact 1134 (0+4), upper right-hand contact 1618 (18) 55 to ground; battery, through the winding of register 1140, upper right-hand contact 1144 (0+4), upper left-hand contact 1618 (18) to ground; battery, through the winding of register 1150, upper right-hand contact 1154 (0+4), upper left-hand contact 1617 (18) 60 to ground; battery, through the winding of register 1160, upper right-hand contact 1164 (0+16), upper right-hand contact 1617 (18) to ground; battery, through the winding of register 1170, upper right-hand contact 1174 (0+16), lower right-hand contact 1616 (18) to ground, and battery, through the winding of register 1180, upper left-hand contact 1184 (0+7), and lower left-hand contact 1616 (18) to ground. 65

When the registers have all been restored to their normal positions and provided the sender sequence switch 1500 has reached its position 1, a circuit is closed as follows for returning the controlling sequence switch 1600 to position 1: battery, through the winding of sequence switch magnet 1600, upper contacts 1612 (18), lower contact 1101 (1), lower contact 1111 (N), and thence through the normal contacts of the remaining registers in series to conductor 1139, upper right-hand and lower left-hand contacts 1622 (18), left-hand contacts 1520 (1) to ground. The sender and registers at the tandem office have thus been completely restored to their normal position. 70 75 80 85 90 95

Completion of connection and application of ringing current.

It will be recalled that during the operation of the final selector switch in Fig. 10, the relay 901 at the incoming selector switch is maintained energized. After the units selection has been completed and sequence switch 1000 moves from position 6 into position 9, it opens at the lower right-hand contact 1009 (1+8½), the holding circuit of relay 901. Relay 901 thereupon releases and closes a circuit from ground through its outer armature and back contact, lower left-hand contact 926 (8), winding of sequence switch magnet 900 to battery and ground. Sequence switch 900 leaves position 8 and advances into position 11. Since at this time the sequence switch 700 at the district selector in the tandem office has advanced into its talking position, and provided the connection has not been abandoned at the originating office, and consequently relays 703 and 704 are still energized, a circuit is closed for 100 relay 902 at the incoming selector switch in the terminating office. This circuit may be traced from battery through contact 922 (11+17), right-hand winding of relay 902, normal contact 956 of relay 903, upper left-hand winding of repeating coil 914, right-hand contacts 916 (9+16), conductor 829, terminal 825, brush 822, conductor 805 (8), conductor 831, terminal 723, brush 720, lower right-hand contact 756 (1+16), upper left-hand contact 756 (16+17), winding of relay 706, outer right-hand armature and contact of relay 705, upper left-hand contact 757 (16+17), lower right-hand contact 757 (1+16), brush 721, terminal 724, thence over 110 115 120 125 130

the lower side of the trunk line to conductor 830, right-hand contacts 917 (9+16), lower left-hand winding of repeating coil 914, normal contact 957 of relay 903, left-hand winding of relay 902 to ground. Relay 902 becomes energized but the current flowing in this circuit is in such a direction as not to affect the polarized relay 706 at the tandem office. Relay 902 closes a circuit from ground through its armature and front contact, upper left-hand contact 923 (7+11), lower left-hand contact 923 (11), left-hand winding of relay 901 to battery and ground at the lower left-hand contact 928. Relay 901 attracts its armatures and completes a circuit from battery through the winding of sequence switch magnet 900, upper left-hand contact 927 (11), front contact and outer armature of relay 901 to ground. Sequence switch 900 leaves position 11 and moves into position 13 and relay 901 becomes deenergized. In position 13 of sequence switch 900, ringing current is immediately applied to the called line. To accomplish this, relay 911 is energized by means of a circuit from battery through the left-hand contact 928, winding of relay 911, right-hand armature and back contact of relay 909, contact and armature of relay 910 to ground at the front contact and armature of relay 902. It will be noted that a circuit in parallel to the one just traced extends through the winding of relay 909, but since this relay is shunted by the direct circuit to ground over the armature and contact of relay 910, it does not operate. Relay 911, however, attracts its armatures and a ringing circuit is established from source 960, upper contact 933 (13+14), winding of relay 910, front contact and lower armature of relay 911, upper contact 934, (13+15), brush 943, terminal 946, conductor 953, thence over the line through the called subscriber's substation, returning by way of conductor 952, terminal 945, brush 942, contact 954 (13+15), front contact and upper armature of relay 911 to ground. Relay 910, being marginal, does not operate in series with the high resistance of the magnet of the substation ringer. As soon after sequence switch reaches position 13 as the constantly rotating cam 912 closes the contact 958, a circuit is completed from ground through said contact, lower right-hand contact 921 (13), winding of relay 903 to battery and ground. Relay 903 becomes energized and opens the contacts 956 and 957. Relay 902, however, is maintained energized in a circuit from battery through its right-hand winding, make-before-break contact 956, inner right-hand armature of relay 903, right-hand contact 920 (13+14), upper left-hand winding of repeating coil 914, thence over the other side of the line through relay 706, and returning over the lower side of the line, as above described, through the lower left-hand winding of repeating coil 914, left-hand contact 919 (13+14), left-hand armature of relay 903, make-before-break contact 957 to ground through the left-hand winding of relay 902. It will be noted that current flows in the same direction in this circuit and that relay 706, therefore, remains inert. Relay 903 also closes a circuit from ground through the lower right-hand and upper left-hand contact 924, outer right-hand armature and contact of relay 903, winding of sequence switch magnet 900 to battery and ground, driving said sequence switch out of position 13 and into position 14. A definite interval after the closure of contact 958, the rotating cam 912 advances to a point where it closes the contact 959. A circuit is now established to ground through contact 959, left-hand contact 921 (14), winding of relay 903 to battery and ground. Relay 903 again attracts its armatures and sequence switch 900 is driven out of position 14 and into position 15. In this position the ringing circuit is connected over the lower contact 933 (14+15), through the constantly rotating interrupter 948 and the ringing source 961, and the called subscriber's bell is rung at regular intervals.

On the response of the called subscriber, by removing his receiver from the switch-hook, the resistance in series with relay 910 is reduced in the well-known manner to permit the energization of said relay. Relay 910 removes the short-circuit from around the relay 909, and this latter relay operates in series with relay 911. Immediately that relay 909 attracts its armatures, a circuit is closed from battery through the left-hand contact 928, front contact and armature of relay 909, winding of said relay to ground at the front contact and armature of relay 902. This circuit shunts the battery current away from relay 911, permitting said relay to release its armatures and complete the talking circuit through to the right-hand windings of repeating coil 914, the supervisory relay 907 in the called loop is now energized, and a circuit is established from battery through the winding of relay 903, armature and contact of relay 907 to ground at the front contact and armature of relay 902. This time the operation of relay 903 reverses the battery current through the winding of relay 902, due to the fact that the right-hand contact 920, and the left-hand contact 919 are opened in position 15 of sequence switch 900.

The reversal of current through the windings of relay 902 causes the energization of polarized relay 706 at the district switch in the tandem office. Relay 706 completes a circuit from ground through its armature and contact, retardation coil 707, inner right-hand armature and contact, of relay 705, upper contact 727 (15+17), conductor 130

156, terminal 137, brush 134, lower right-hand contact 154 (11+16), lower left-hand contact 154 (12+16), winding of relay 115, through the lower right-hand winding of 5 repeating coil 112 to battery and ground. The supervisory relay 115 operates in this circuit and closes a circuit from ground through its contact and armature, upper left-hand contact 148 (14), contact 206 10 (11+15), conductor 158, winding of sequence switch magnet 100 to battery and ground. The sequence switch 100 at the district selector in the originating office therefore advances to the talking position 15 16. The lamp 121, which up to this time has been burning steadily to indicate the progress of the extended connection, is extinguished and a circuit is closed from battery through resistance 161, lamp 120, left-hand 20 contact 149 to ground. Lamp 120, however remains extinguished being shunted by a circuit from battery, resistance 161, resistance 165, lower right-hand contact 148 (15+16), to ground at the armature and 25 contact of relay 115. The desired connection has thus been completely established and conversation may take place. Talking current is furnished to the calling line through the windings of repeating coil 112, 30 and to the called line through the windings of repeating coil 914.

Release of connection.

After the conversation has ended, the calling subscriber replaces his receiver on the switchhook and the calling supervisory relay 113, in the originating office, deenergizes. The shunt is now removed from around the supervisory lamp 114, and said lamp illuminates to advise the operator that the calling subscriber has hung up his receiver. The operator thereupon releases the connection by removing plug 105 from jack 104. The removal of the plug from the jack causes 40 the deenergization of relay 107, which completes a circuit from ground through its armature and back contact, lower left-hand contact 211 (11), winding of sequence switch magnet 200 to battery and ground. 45 Sequence switch 200 advances out of position 11 into position 12, from whence it is driven into position 17 by means of a circuit closed at the upper right-hand contact 212 (12+14). Sequence switch 200 is now 50 driven into its normal position 1 by means of a circuit from battery through the windings of said sequence switch, upper right-hand contact 211 (11+17), lower left-hand contact 211 (17+1), conductor 164 to 55 ground at the back contact and armature of relay 107. In position 1 of sequence switch 200 a circuit is established from battery through the winding of relay 118, right-hand contact 141 (2+18), conductor 163, 60 upper left-hand contact 211 (1), lower left-

hand contact 211 (17+1), conductor 164, back contact and armature of relay 107, to ground. Relay 118 energizes and locks up in a circuit through its front contact and right-hand armature to ground. Relay 118 70 also closes a circuit from ground through its left-hand armature and front contact, upper right-hand contact 144 (12+18), upper left-hand contact 144 (11+17), winding of sequence switch magnet 100 to battery and 75 ground. Sequence switch 100 thereupon advances into position 18. The downdrive power magnet 124 is now energized and the brush shaft is returned to its normal position. The circuit through magnet 124 may 80 be traced from battery through the winding of said magnet, lower right-hand contact 144 (18), upper right-hand contact 144 (12+18) to ground at the front contact and left-hand armature of relay 118. When the 85 brush shaft reaches its normal position, a circuit is closed from battery through the winding of sequence switch magnet 100, upper right-hand contact 143 (4+18), segment 132, brush 131, lower right-hand contact 139 (8+6) to ground. Sequence switch 100 moves out of position 18 and into position 1, and the circuit of magnet 124 is opened. Relay 118 also deenergizes when 90 sequence switch 100 leaves position 18. 95

When sequence switch 100 moves out of position 16, the upper contacts 153 are opened and relay 703, at the tandem office, is deenergized. Relay 703 opens the circuit of relay 705, which in turn opens the circuit of relay 704. Relay 704, at its left-hand armature and contact opens the energizing circuit of relay 702. Relay 702 completes a circuit from ground through its right-hand armature and back contact, lower left-hand contact 732 (16+17), winding of sequence switch magnet 700 to battery and ground. Sequence switch 700 leaves position 16 and advances through position 17 and into position 18. In this position the downdrive power magnet 700 is energized and the brush shaft of the district selector switch is restored to normal. The circuit for magnet 711 leads from battery through the winding of said magnet, lower left-hand contact 738 (18), upper left-hand contact 739 (18) to ground. When the brush shaft has been 100 fully restored, a circuit is closed from battery through the winding of sequence switch magnet 700, upper right-hand contact 732 (9+18), segment 716, brush 717 to ground. Sequence switch 700 leaves position 18, 105 opening the circuit of magnet 711, and advances into position 1. 110

When sequence switch 700 leaves position 125 16, it opens, at its upper left-hand contact 739, the holding circuit of relay 801 at the office selector switch. Relay 801 deenergizes and completes a circuit from ground through its left-hand armature and back contact, up- 130

per left-hand contact 809 (8+17), winding of sequence switch magnet 800 to battery and ground. Sequence switch 800 is driven into position 18 where the downdrive power magnet 803 is energized and the brush shaft at the office switch restored to its normal position. The circuit of magnet 803 may be traced from the winding of said magnet, lower right-hand contact 811 (18) to ground. When the switch has reached its normal position, a circuit is closed from battery through the winding of sequence switch magnet 800, upper right-hand contact 809 (3+18), segment 821, brush 819 to ground. Sequence switch 800 moves from position 18 to position 1, and the circuit of magnet 803 is opened.

At the time the relay 705 at the district switch releases its armatures, the circuit through the winding of relay 902 is opened and this relay deenergizes. As soon after the deenergization of relay 902 as the constantly rotating cam 913 closes the contact 962, a circuit is closed from battery through the winding of relay 915, left-hand armature and contact of relay 909, upper left-hand contact 925 (15+17), contact 962 to ground. Relay 915 operates and closes a holding circuit for itself from battery through the winding of said relay, left-hand armature and contact of relay 909, lower left-hand contact 925 (15+17), contact and outer left-hand armature of relay 915 to ground at the back contact and armature of relay 902. The contact 962 is opened by the continued rotation of cam 913, and at the end of a definite interval contact 963 is closed. A circuit is now established from battery through the lower left-hand contact 928 (2 $\frac{3}{4}$ +18), left-hand winding of relay 901, right-hand armature and contact of relay 915, contact 963 to ground. Relay 901 operates and closes a holding circuit through its front contact and left-hand armature, lower right-hand contact 923 (12+17), upper right-hand contact 923 (15+17), to ground. Relay 901 also closes a circuit as follows for driving sequence switch 900 out of position 15, through position 17, and into position 18: battery through the winding of the magnet of said sequence switch, upper left-hand contact 927 (15+17), front contact and outer armature of relay 901 to ground. In position 18 of sequence switch 900, the downdrive power magnet 905 is energized and the brush shaft of the switch 950 is restored to its normal position. The circuit of magnet 905 may be traced from battery to the winding of said magnet, lower right-hand contact 930 (18), lower left-hand contact 930 (7+5) to ground. When the switch reaches its normal position, a circuit is closed from battery through the winding of sequence switch magnet 900, lower right-hand contact 926 (3+18), seg-

ment 941, brush 935 to ground through the lower left-hand contact 930 (7+5). Sequence switch 900 leaves position 18, opens the circuit of power magnet 905, and advances into its normal position 1. 70

The sequence switch 900, in moving out of position 15 $\frac{1}{4}$, opens, at its upper right-hand contact 932, the holding circuit of relay 1002, and said relay deenergizes. A circuit is now closed to battery through the left-hand winding of relay 1001, upper contacts 1013, back contact and right-hand armature of relay 1002 to ground. Relay 1001 attracts its armatures and closes a circuit from battery through the winding of sequence switch magnet 1000, lower right-hand contact 1015 (15), front contact and left-hand armature of relay 1001, upper left-hand contact 1014 (12 $\frac{3}{4}$ +16) to ground. Sequence switch 1000 advances into position 16 and relay 1001 releases its armatures. A circuit is then closed over the upper right-hand contact 1015 (16), and the back contact and left-hand armature of relay 1001, for driving said sequence switch into position 17. 80 Sequence switch 1000 immediately moves into position 18 by means of a circuit from battery through the winding of said sequence switch, lower right-hand contact 1013 (17), upper left-hand contact 1013 (14+17) to ground through the back contact and right-hand armature of relay 1002. The downdrive power magnet 1006 is now energized and the brush shaft of the final selector switch 1050 is restored to its normal position. 85 The circuit for magnet 1006 may be traced from battery through the winding of said magnet, lower right-hand contact 1018 (18), upper right-hand contact 1017 (18), upper left-hand contact 1019 (13+11) to ground. When the switch shaft reaches its normal position, a circuit is completed from battery through the winding of sequence switch 1000, upper left-hand contact 1015 (18), segment 1038, brush 1023, upper left-hand contact 1019 (13+11) to ground. Sequence switch 1000 leaves position 18, opens the circuit of power magnet 1006, and advances into its normal position 1. All apparatus taken for use in the extension of the 90 connection has now been restored and may be utilized for subsequent calls. 100

Called line tests busy.

It will next be assumed that the called 120 subscriber's line is busy at the time the final selector switch seizes the terminals thereof. In the manner already described, the units selecting operation takes place in position 6 of sequence switch 1000, following which the relay 1001 releases its armatures and completes a circuit for advancing said sequence switch out of position 6 and into position 9. A busy subscriber's line is identified by the existence of full battery 125 130

potential on the test terminal 1034 thereof. In case the line is made busy as a called line, this potential is supplied over the following circuit: battery, through the right-hand contact 1020 (11+17), resistance 1039, lower left-hand contact 1021 (15+17), lower right-hand contact 1021 (11+16 $\frac{1}{2}$), brush 1031 to the test terminal 1034. As sequence switch 1000 reaches position 8 $\frac{1}{4}$, the above traced circuit is closed through the right-hand winding of relay 1001, lower right-hand and upper left-hand contacts 1016 to ground at the front contact and right-hand armature of relay 1002, and sequence switch 1000 is driven from position 9 into position 12. Relay 1001 is held energized through position 10 of sequence switch 1000 by the circuit from battery through the left-hand contact 1020 (1+10), right-hand winding of relay 1001, lower right-hand contact 1016 (15+10), front contact and right-hand armature of relay 1001, upper right-hand contact 1021 (1+15), upper left-hand contact 1021 (9+10), to ground. This circuit is opened as sequence switch 1000 leaves position 10, but relay 1001 is now maintained energized in a circuit from battery through its left-hand winding, lower right-hand contact 1012 (10+11), front contact and left-hand armature of relay 1001, to ground through the upper left-hand contact 1014 (1+11). When sequence switch 1000 reaches position 11, a test is made to ascertain the condition of the terminals of the called subscriber's line. Since the called line is busy a battery potential is present on terminal 1034, and the following circuit is closed: battery, terminal 1034, brush 1031, lower right-hand contact 1021 (11+16 $\frac{1}{2}$), upper right-hand contact 1021 (1+15), right-hand armature and front contact of relay 1001, upper right-hand contact 1016 (11+12 $\frac{1}{2}$), right-hand winding of relay 1001, lower left-hand contact 1010 (11+13), upper left-hand contact 1008 (11+13), winding of relay 1003 to ground. Relay 1001, therefore, remains energized in this test circuit when sequence switch 1000 leaves position 11 and opens the above traced circuit through the left-hand winding of said relay. Furthermore, relay 1003 attracts its armature and opens the above traced holding circuit through the left-hand winding of relay 1002. Relay 1002 thereupon deenergizes and when sequence switch 1000 reaches position 12, a circuit is closed from ground through the right-hand armature and back contact of relay 1002, upper left-hand contact 1013 (2+12), lower right-hand contact 1013 (1+13), winding of sequence switch magnet 1000 to battery and ground, for driving said sequence switch out of position 12 and into position 13. In this position relay 1002 is again energized in a circuit from battery through its left-

hand winding, conductor 1037, upper right-hand contact 1019 (13) to ground. Relay 1002 closes a circuit from ground through its right-hand armature and front contact, lower left-hand contact 1013 (13), and lower right-hand contact 1013 (1+13), for driving sequence switch 1000 out of position 13 and into position 14. As sequence switch 1000 leaves position 13, it opens the above traced test circuit and relay 1003 becomes deenergized, but relay 1001 is now held in its actuated condition by means of a circuit from battery through the left-hand winding of relay 1001, lower right-hand contact 1012 (12 $\frac{3}{4}$ +14), front contact 80 and left-hand armature of relay 1001 to ground at the upper left-hand contact 1014 (12 $\frac{3}{4}$ +16). When, therefore, sequence switch 1000 reaches position 14, a circuit is closed as follows for the downdrive power 85 magnet 1006, and the brush shaft of the final selector switch is restored to its normal position. This circuit leads from battery through the winding of said magnet, lower right-hand contact 1018 (14), front 90 contact and left-hand armature of relay 1001, upper left-hand contact 1014 (12 $\frac{3}{4}$ +16) to ground. As the switch shaft reaches its normal position, the above traced circuit is closed over the upper left-hand contact 95 1015 (3+16), and the normal position segment 1038, for driving sequence switch 1000 out of position 14, through positions 15 and 16, into position 17. In position 17 of sequence switch 1000, a circuit is closed from battery through the left-hand winding of relay 1001, upper left-hand contact 1012 (17), interrupter 1035 to ground. Relay 1001 is intermittently energized and deenergized. 105

In the meantime the incoming selector switch 950 has advanced from position 8 into the ringing position 15, in the manner hereinbefore explained. Therefore, for each energization of relay 1001 under the control of interrupter 1035, a circuit is closed from ground through the right-hand winding of the tone coil 1036, lower right-hand contact 1014 (17), left-hand armature and front contact of relay 1001, upper left-hand contact 1018 (17), lower right-hand contact 1018 (17), lower right-hand contact 1009 (17), upper left-hand contact 1009 (17+15), conductor 953, terminal 946, brush 943, upper contact 934 (13+15), lower armature 110 and front contact of relay 911, winding of relay 910, to ground through the ringing source 961. The marginal relay 910 receives sufficient current from this circuit to operate. The ringing operation is thereby discontinued and relay 911 retracts its armatures. When relay 911 becomes deenergized, the circuit just traced through the primary winding of the tone coil 1036 is now extended 115 over the lower armature and back contact of 120 125 130

relay 911, winding of relay 907, lower right-hand winding of repeating coil 914 to battery and ground. Relay 907, is therefore, energized and deenergized in synchronism with the interrupter 1035. Each time relay 907 attracts and retracts its armatures, current is reversed through the windings of relay 902, and the polarized relay 706, at the district switch in the tandem office, is operated. The first attraction of the armature of relay 706 operates the supervisory relay 115 at the district switch in the originating office, which causes the sequence switch 100 to advance from position 14 into position 16. For each succeeding deenergization of relay 706, the relay 115 is deenergized and, at its armature and contact, removes the shunt from around the supervisory lamp 120, whereby said lamp is illuminated. The flashing of lamp 120 advises the operator that the called line is busy. She then depresses the key 216, which closes a circuit from battery through the lower right-hand and upper left-hand contacts 210, winding of relay 217, contacts of key 216 to ground. Relay 217 closes a circuit from battery through the winding of sequence switch magnet 200, right-hand contacts 211 (11+17), contact and left-hand armature of relay 217 to ground, driving sequence switch 200 out of position 11 and into position 1. Sequence switch 200, immediately advances into the listening-in position 7 by means of a circuit from battery through the winding of the magnet of said sequence switch, upper left-hand contact 212 (1), conductor 157, front contact and armature of relay 107 to ground. The operator now communicates with the calling subscriber, advising him that the called line is busy and thereafter proceeds to release the connection as hereinbefore described in detail.

In response to the release of the incoming selector switch, the relay 1002 deenergizes in the manner explained and completes a circuit over its right-hand armature and back contact, upper left-hand contact 1013 (14+17), lower right-hand contact 1013 (17), winding of sequence switch magnet 1000, for driving said sequence switch into position 18. Since the final selector switch has already been restored, sequence switch 1000 is immediately driven into position 1 over the circuit already traced.

55 *Release when all trunks are found busy.*

If during the trunk hunting operation of any of the selector switches all trunks in the group are found to be busy, the connection 60 is automatically released and a signal transmitted to the operator in the originating office to advise her of this fact. To explain the manner in which release takes place under these conditions, it will be assumed that 65 all trunks in the selected group at the in-

coming switch 950 are busy at the time the trunk hunting operation takes place. The brushes 942, 943, and 944 are, therefore, moved over the entire group and come to rest on a set of over-flow terminals, shown at 964, 70 965, and 966. The test terminal 966 of the over-flow set has no ground potential thereon, and therefore 901 deenergizes and the switch comes to rest. Sequence switch 900 thereupon advances from position 6 into position 7. The segments on the upper portion of commutator 938 are so arranged that the brush 936 is in engagement with one of such segments when brushes 942, 943, and 944 are standing on a set of over-flow terminals. 75 Consequently a circuit is closed from battery through the winding of sequence switch magnet 900, upper left-hand contact 926 (7), commutator 938, brush 936 to ground at the left-hand contact 930. Sequence switch 900 80 advances from position 7 into position 8, and since relay 901 is deenergized at this time, a circuit is closed from battery through the winding of said sequence switch, lower left-hand contact 926 (8), back contact and 85 outer armature of relay 901 to ground. Sequence switch 900 thereupon advances from 90 position 8 into position 11. In this position the above traced circuit is closed over the upper left-hand contact 926 (11+16) to 95 ground and sequence switch 900, is advanced into position 17.

It will be recalled that the sender sequence switch 1500 moves in position 6, following the group selecting operation at the incoming switch 950. When, therefore, sequence switch 900 reaches position 11, a circuit is completed from battery through contact 922 (11+17), right-hand winding of relay 902, make-before-break contact 956, upper left-hand winding of repeating coil 914, right-hand contacts 916 (9+16), conductor 829, thence over the circuit above traced through the stepping relay 1506, left-hand winding of relay 1505, and by way of conductor 830, 100 right-hand contacts 917 (9+16), lower left-hand winding of repeating coil 914, make-before-break contacts 957, left-hand winding of relay 902 to ground. Relay 902 becomes energized but, as above explained, the 105 direction of the flow of current in this circuit is such as not to affect the relay 1505 at the sender. When later sequence switch 900 is passing through positions 13 to 15, a circuit is closed from battery through the lower right-hand winding of repeating coil 914, winding of relay 907, back contact and lower armature of relay 911, upper contact 934 (13+15), brush 943 to the grounded over-flow terminal 965. Relay 907 operates and 110 closes a circuit from battery through the winding of relay 903, armature and contact of relay 907, front contact and armature of relay 902 to ground. Relay 903 attracts its armatures and, in the manner above de- 115 120 125 130

- scribed, reverses the direction of the flow of current through the windings of relay 902. This reversal of current causes the operation of relay 1505 at the sender, the function 5 of which will be presently described. On reaching position 17, sequence switch 900 immediately advances into position 18, and the selector switch is restored to its normal position in the manner hereinbefore described.
- 10 Relay 1505 at the sender, on energizing, closes a circuit from ground through its armature and contact, winding of relay 1605 to battery and ground. Relay 1605 attracts its armatures and locks up in a circuit over its 15 inner left-hand armature and contact and the upper left-hand contact 1628 (3+17) to ground. Relay 1605 also closes a circuit from battery through the winding of sequence switch 1600, lower left-hand contact 20 1627 (13+14), contact and outer left-hand armature of relay 605 to ground, driving said sequence switch out of position 14 and into position 17. In this position of sequence switch 1600, the district selector sequence 25 switch 700 is advanced from position 15 into position 16 by means of a circuit from battery through the winding of sequence switch magnet 700, lower right-hand contact 743, left-hand armature and back contact of relay 701, lower left-hand contact 734 (15), lower right-hand contact 734 (14+15), lower right-hand contact 748 (1), conductor 763, contact and inner right-hand armature of relay 1602, right-hand contacts 1624, closed 30 in position 17, to ground at the contact and outer left-hand armature of relay 1605. A circuit is now closed from ground through the left-hand winding of relay 701, upper left-hand contact 785 (16), conductor 764, lower right-hand contact 747 (1), conductor 40 765, contact and inner right-hand armature of relay 1603, right-hand contacts 1630 (13+17), contact and inner right-hand armature of relay 1605, lower right-hand contact 45 747 (13+17) to ground. Relay 701 becomes energized in this circuit and completes a circuit from battery through the winding of sequence switch 700, lower left-hand contact 50 743 (16), front contact and left-hand armature of relay 701, lower left-hand contact 739 (16), upper left-hand contact 739 (1+16), to ground, driving sequence switch 700 into position 17. It will be remembered that in 55 the regular operation of the system, when the district sequence switch 700 leaves position 15, the holding circuit of relay 1602 is opened, permitting this relay, and consequently relays 1603 and 1604, to release.
- 60 On an overflow disconnection, however, relay 1603 is maintained energized after the sequence switch 700 leaves position 15 in order to permit the establishment of the circuit above traced for relay 701, which causes the 65 advance of sequence switch 700 from posi-
- tion 16 into position 17. To accomplish this, the relay 1602 is maintained energized after sequence switch 700 leaves position 15 in the following circuit: battery, through the winding of relay 1602, front contact and left-hand armature of said relay, lower contact 1621, conductor 762, lower left-hand contact 753 (18+2), lower right-hand contact 753 (14+14), lower right contact 736 (15+16), upper right-hand contact 736 (3+16), lower 75 right-hand contact 749 (1), conductor 766, contact and outer left-hand armature of relay 1603, contact and outer right-hand armature of relay 1605, lower right-hand and upper left-hand contacts 1626 to ground. 80 Therefore, sequence switch 700 advances, as described, to position 17, and on leaving position 16 opens the circuit just traced to permit the deenergization of relay 1602, which in turn permits the release of relays 1603 85 and 1604. From this point on the release of the register sender at the tandem office is substantially similar to that already described.
- 90 In position 17 of sequence switch 700, a circuit is established from battery through the interrupter 708, upper right-hand contact 756 (17), upper left-hand contact 756 (16+17), winding of the polarized relay 706, outer right-hand armature of relay 705, upper left-hand contact 757 (16+17), upper right-hand contact 757 (17), to ground. Each time the interrupter 708 closes, current flows through the winding of relay 706 in the proper direction to operate the same. 95 Relay 706 attracts and releases its armatures and, in the manner already explained, the relay 115, at the originating office, operates to open and close the shunt around the supervisory lamp 120. The timing of the 100 interrupters 708 and 1035 may be so taken as to cause the lamp 120 to flash at different rates. In this way the operator is able to distinguish between the failure of the call, due to the wanted line being busy, 105 and the failure, due to all trunks in a group being simultaneously engaged. Upon observing the flashing of lamp 120 under the control of interrupter 708, the operator may 110 inform the calling subscriber that the connection cannot be obtained and proceed to release the switches.
- 115 For the particular called office involved in the present discussion, the code number of which is 3 5 3, it has been seen how the 120 intermediate registers 1100, 1110, and 1120, at the tandem office, are set in positions 5, 5, and 3. The setting of these registers causes the tripping of the third set of brushes of the translator switch 1260, and also the 125 operation of said switch to position the set of brushes on a set of terminals in the second group of twenty. Had the called office belonged to the first group of 200 offices served through the tandem point, the trans-

lator switch 1250 would be used. For any of this group of 200 offices, the digits of the office code would be such as to cause the register 1100 to take up a setting either in position 2 or position 3. From an inspection of the circuits it will be found that with register 1100 in position 2, or in position 3, the upper right-hand contact 1211 is closed instead of the lower right-hand contact 1211, and consequently relay 1203 is operated instead of relay 1204. In the manner identical with that described for relay 1204, relay 1203 causes the selection of the translator switch 1250 for use.

With the register 1100 in position 5, the relay 1106 is operated in the manner already explained, and translator switch 1260 is caused to position its brushes on a set of terminals in the second group of 200, to effect a registration on the relay registers necessary to cause the selection of the desired office in the second group of 200 called offices. It will be recalled that the energizing circuit of relay 1106 was closed over the upper left-hand contact 1211 in position 5. In a similar manner, when register 1100 takes up a setting in position 3, and the translator switch 1250 is taken for use, relay 1106 is also energized to cause the translator switch 1250 to position its brushes on the set of terminals in the second group of twenty, to effect a registration on the relay registers for controlling the extension of a connection to the desired one in the first group of 200 called offices. When, however, the register 1100 is set in either positions 2 or 4, the upper left-hand contact 1211 is opened, relay 1106 does not operate, and consequently translator switches 1250 and 1260 are caused to position their brushes on the set of terminals in the first group of twenty to effect the required registration. Referring to the circuits, if relay 1106 is de-energized, the brush 1231 of translator switch 1260, for example, on engaging the first terminal 1289, closes a circuit from ground through the upper left-hand contacts 1128 (8 $\frac{3}{4}$ +9), right-hand armature and back contact of relay 1106, terminal 1289, brush 1231, and thence, as hereinbefore traced, to the winding of relay 1200. The translator switch 1260, therefore, comes to rest. The register 1100 advances and on the next upward movement of the translator switch a set of terminals in the first group of twenty is selected.

While the registering mechanism at the tandem office is described in this application as having a capacity for controlling the selection of any one of four hundred different outlying offices, it is to be understood that this capacity might readily be increased by enlarging the size of the translator switches 1250, by adding other translator switches, or in any other desirable manner.

According to the principle of tandem switching employed in this system, the portion of the entire designation which represents the called office is used, first, to route the call to the tandem point and then is used over again at the tandem point to further route the call in the proper direction therefrom. As has been explained in detail hereinbefore, the office code which is utilized for these two different purposes comprises the first three digits or characters, usually letters. This office code is recorded in the initial office, as explained on the registers 400, 410 and 420, to determine the selection of the trunk outgoing to the tandem point. Thereafter the record of the office code is transferred over the selected trunk to the tandem point and there set up again to govern the selection of a trunk outgoing from the tandem point to the called office. Analyzing this plan, it will be seen that a large number of different office codes may serve at the initial office to select trunks of the same general character all leading into the same tandem switching point. At the tandem office, however, these different office codes when received and recorded will each have its own separate identity for the purpose of determining the selection of a trunk outgoing from the tandem point to different outlying called offices.

What is claimed is:

1. In a telephone system, automatic switches for extending telephone connections, a variably operable register, impulse means for setting said register, a variably operable selective switch, means controlled by said register for positioning said selective switch, a sender mechanism, means rendered effective by said selective switch while in its set position for determining the operation of said mechanism in accordance with such position, and means controlled by the sender mechanism for selectively operating said automatic switches.

2. In a telephone system, automatic switches for extending telephone connections, a variably operable register, impulse means for setting said register in accordance with a desired designation, a variably operable selective switch, means controlled by said register for positioning said selective switch in accordance with the desired designation, a sender mechanism, means rendered effective by said selective switch while in its set position for determining the operation of said mechanism in accordance with such position, and means controlled by the sender mechanism for selectively operating said automatic switches.

3. In a telephone system, automatic switches for extending telephone connections, a variably operable register, impulse means for setting said register, a selective switch having brushes and sets of stationary

terminals, means controlled in accordance with the setting of said register for operating said brushes to select a set of terminals, a sender mechanism, means rendered effective by said selective switch while in its set position for determining the operation of said mechanism depending on the set of terminals selected by said brushes, and means controlled by the sender mechanism for operating said automatic switches.

4. In a telephone system, automatic switches for extending telephone connections, a plurality of variably operable registers, impulse means for setting said registers, a variably operable selective switch, means controlled by said registers for positioning said selective switch, a sender mechanism, means rendered effective by said selective switch while in its set position for determining the operation of said mechanism in accordance with such position, and means controlled by the sender mechanism for selectively operating said automatic switches.

5. In a telephone system, automatic switches for extending telephone connections, a plurality of variably operable registers, impulse means for setting said registers in accordance with desired designations, a variably operable selective switch, means controlled by said registers for positioning said selective switch, a sender mechanism, means rendered effective by said selective switch while in its set position for determining the operation of said mechanism in accordance with the position taken by such switch, and means controlled by the sender mechanism for selectively operating said automatic switches.

6. In a telephone system, automatic switches for extending telephone connections, a plurality of variably operable registers, means for transmitting series of impulses representing desired designations for setting said registers, a variably operable selective switch, means controlled by said register for positioning said selective switch, a sender mechanism, means rendered effective by said selective switch while in its set position for determining the operation of said mechanism in accordance with the position taken by such switch, and means controlled by the sender mechanism for operating said automatic switches.

7. In a telephone system, a plurality of offices, automatic switches, a plurality of variably operable registers, impulse means for setting said registers, a variably operable selective switch, means controlled by said registers for positioning said selective switch, a sender mechanism, means rendered effective by said selective switch while in its set position for determining the operation of said mechanism in accordance with such position, and means controlled by the sender mechanism for selectively operating said au-

tomatic switches to extend a connection to any one of said offices.

8. In a telephone system, a plurality of offices, automatic switches, a plurality of variably operable registers, impulse means for setting said registers in accordance with the designation of any of said offices, a variably operable selective switch, means controlled by said registers for positioning said selective switch, a sender mechanism, means rendered effective by said selective switch while in its set position for determining the operation of said mechanism in accordance with the position taken by such switch, and means controlled by the sender mechanism for selectively operating said automatic switches to extend a connection to the office the designation of which is recorded on said registers.

9. In a telephone system, an automatic switch, means for extending a telephone connection to said automatic switch, a plurality of variably operable registers, means for associating said registers with the extended connection, impulse means for setting said registers, a variably operable selective switch, means operated in accordance with the settings of said registers for positioning the selective switch, a sender mechanism, means rendered effective by said selective switch while in its set position for determining the operation of the sender mechanism in accordance with the position of said selective switch, and means controlled by the sender mechanism for operating said automatic switch to further extend the telephone connection.

10. In a telephone system, automatic switches, means for extending a telephone connection to said switches, a plurality of variably operable registers, means for associating said registers with the extended connection, means for transmitting impulses over said connection to determine the setting of said registers, a variably operable selective switch, means operated in accordance with the settings of said registers for positioning said selective switch, a sender mechanism, means rendered effective by said selective switch while in its set position for determining the operation of said mechanism in accordance with such position, and means controlled by the sender mechanism for operating said automatic switches to further extend the telephone connection.

11. In a telephone system, automatic switches for extending telephone connections, a plurality of variably operable registers, impulse means for setting said registers, a variably operable selective switch, means controlled by said registers for positioning said selective switch, a sender mechanism, means rendered effective by said selective switch while in its set position for determining the operation of said mechanism

- nism in accordance with such position, means for releasing said selective switch, and means controlled by the sender mechanism for selectively operating said automatic switches.
12. In a telephone system, automatic switches for extending connections, a plurality of variably operable registers, impulse means for setting said registers, a variably operable selective switch, means controlled by said registers for positioning said selective switch, a sender mechanism, means rendered effective by said selective switch for determining the operation of said mechanism in accordance with the position taken by said switch, means controlled by the sender mechanism for operating said automatic switches, means controlled by the sender mechanism for releasing said selective switch, and means operated by said sender mechanism following the operation of said automatic switches for restoring said registers to their normal position.
13. In a telephone system, automatic switches for extending connections, a plurality of variably operable registers, impulse means for setting said registers, a variably operable selective switch, means controlled in accordance with the joint settings of said registers for positioning said selective switch, a sender mechanism, means dependent upon the position taken by said selective switch for determining the operation of said sender mechanism, and means controlled by said sender mechanism for selectively operating said automatic switches.
14. In a telephone system, automatic switches, means for extending a connection to said switches, a plurality of variably operable registers, means for transmitting impulses over said connection to set said registers, a variably operable selective switch, means operated in accordance with the joint settings of said registers for positioning said selective switch, a sender mechanism, means dependent upon the position taken by said selective switch for determining the operation of the sender mechanism, and means controlled by the sender mechanism for operating said automatic switches to further extend said connection.
15. In a telephone system, automatic switches, means for extending a connection to said switches, a plurality of variably operable registers, means for transmitting a series of impulses, each representing the digit of a desired designation over the extended connection to determine the setting of each of said registers, a variably operable selective switch, means operated in accordance with the joint settings of said registers for positioning said selective switch, a sender mechanism, means dependent upon the position taken by said selective switch for determining the operation of the sender mechanism, and means controlled by the sender mechanism for operating said automatic switches to further extend said connection.
16. In a telephone system, automatic switches for extending connections, a plurality of variably operable registers, impulse means for setting said registers, a selective switch having movable brushes and sets of stationary terminals, said terminals being arranged in groups, means dependent upon the settings of said registers for operating said brushes to select a group and also a set of terminals, a sender mechanism, means for operating the sender mechanism in accordance with the set of terminals selected by said brushes, and means controlled by said mechanism for operating said automatic switches.
17. In a telephone system, automatic switches for extending connections, a plurality of variably operable registers, impulse means for setting said registers, a selective switch having a plurality of brushes and sets of stationary terminals, said terminals being arranged in groups, one group for each set of brushes, means dependent upon the settings of said registers for operating said switch to select a set of brushes and for moving said brushes into engagement with a set of terminals in the corresponding group, a sender mechanism, means for operating said mechanism in accordance with the set of terminals selected by said brushes, and means controlled by said sender mechanism for selectively operating said automatic switches.
18. In a telephone system, an automatic switch for extending connections, a plurality of variably operable registers, impulse means for setting said registers, a selective switch having a plurality of sets of brushes and stationary terminals, said terminals being arranged in groups, one group for each set of brushes, means dependent upon the setting of one of said registers for selecting a set of brushes for use, means dependent upon the joint settings of said registers for operating said brushes to select a set of terminals in the corresponding group, a sender mechanism, means for variably operating said mechanism in accordance with the set of terminals selected by said brushes, and means controlled by said sender mechanism for operating said automatic switch.
19. In a telephone system, automatic switches for extending connections, a variably operable register, impulse means for setting said register, a plurality of selective switches, means dependent upon the setting of said register for selecting one of said selective switches for use, means for positioning the selective switch, a sender mechanism, means for operating said mechanism in accordance with the setting of said register.

- cordance with the position taken by said selective switch, and means controlled by the sender mechanism for operating said automatic switches.
- 5 20. In a telephone system, automatic switches for extending telephone connections, a plurality of variably operable registers, impulse means for setting said registers, a plurality of variably operable selective switches, means dependent upon the setting of one of said registers for selecting one of said selective switches for use, means dependent upon the joint settings of said registers for positioning the selective switch,
- 10 15 a sender mechanism, means for variably operating said mechanism in accordance with the position taken by said selective switch, and means controlled by the sender mechanism for operating said automatic switches.
- 20 21. In a telephone system, a plurality of offices divided in groups, a plurality of variably operable registers, means for positioning said registers by impulses representing the designations of said offices, a plurality
- 25 of variably operable selective switches, each of said switches corresponding to a group of offices, means dependent upon the setting of one of said registers for selecting for use the selective switch corresponding to a desired group of offices, means dependent upon the joint settings of said registers for positioning said selective switch, a sender mechanism, means for variably operating said mechanism in accordance with the position
- 30 35 taken by said selective switch, automatic switches, and means controlled by said sender mechanism for operating said automatic switches to extend a telephone connection to a particular one of said offices in the desired group.
22. In a telephone system, automatic switches for extending connections, a group of variably operable registers, impulse means for setting said registers, a variably operable selective switch, means dependent upon the settings of said registers for positioning the selective switch, a second group of registers, means controlled by said selective switch while in its set position and in accordance with such position for setting the registers of said second group, and means controlled by said last-mentioned registers for operating said automatic switches.
- 50 55 23. In a telephone system, automatic switches for extending connections, a group of variably operable registers, impulse means for setting said registers, a selective switch, means dependent upon the settings of said registers for positioning said selective switch, a second group of variably operable registers, means controlled by the selective switch while in its set position and in accordance with such position for setting the registers of said second group, a sender mechanism,
- 60 65 means controlled by said last-mentioned registers for determining the operation of the sender mechanism, and means controlled by said sender mechanism for operating said automatic switches.
- 70 24. In a telephone system, automatic switches, means for extending a connection to said switches, a group of variably operable registers, means for transmitting impulses over the extended connection to set said registers, a selective switch, means dependent upon the settings of said registers for positioning the selective switch, a second group of registers, means controlled by the selective switch while in its set position and in accordance with such position for setting the registers of said second group, and means controlled in accordance with the setting of said last-mentioned registers for operating said automatic switches to further extend said connection.
- 75 80 25. In a telephone system, automatic switches for extending connections, a group of variably operable registers, means for transmitting impulses to set said registers, a selective switch, means dependent upon the settings of said registers for positioning the selective switch, a second group of variably operable registers, each register comprising a plurality of relays, means dependent upon the position taken by the selective switch for operating the relays of said second registers, and means controlled by said relays for operating said automatic switches.
- 85 90 26. In a telephone system, automatic switches for extending connections, a group of variably operable registers, impulse means for positioning said registers, a selective switch, means dependent upon the settings of said registers for positioning the selective switch, a second group of variably operable registers, a device for generating impulses, means dependent upon the position taken by the selective switch for transmitting impulses from said device to set the registers of said second group, and means controlled in accordance with the settings of said last-mentioned registers for operating said automatic switches.
- 95 100 27. In a telephone system, automatic switches for extending connections, a group of variably operable registers, impulse means for setting said registers, a plurality of selective switches, means dependent upon the settings of said registers for selecting and positioning one of said selective switches, a second group of variably operable registers, means for setting the registers of said second group in accordance with the position taken by the selective switch, and means controlled by said second registers for selectively operating said automatic switches.
- 105 110 28. In a telephone system, automatic switches for extending connections, a group of variably operable registers, impulse

means for setting said registers, a plurality of selective switches, means dependent upon the joint settings of said registers for selecting and positioning one of the selective switches, an impulse generating device, a second group of registers, means dependent upon the position taken by the selective switch for transmitting impulses from said device to set the registers of said second group, and means controlled by said second group of registers for selectively operating said automatic switches.

29. In a telephone system, automatic switches for extending connections, a group of registers, means for variably setting said registers, a second group of registers, means for setting the registers of said second group in accordance with the settings of said first registers, a selective switch, means dependent upon the settings of said second registers for positioning said switch, and means controlled in accordance with the position taken by said switch for selectively operating said automatic switches.

30. In a telephone system, a group of registers, means for variably setting said registers, a second group of registers, impulse means operable in accordance with the settings of said first registers for setting the registers of said second group, a selective switch, means dependent upon the settings of said second registers for variably positioning the selective switch, and means operated in accordance with the position taken by said selective switch for operating said automatic switches.

31. In a telephone system, an automatic switch, a group of registers, means for variably setting said registers, a second automatic switch, means controlled by said registers for operating said first automatic switch to extend a connection to said second automatic switch, a second group of variably operable registers, means for setting said second registers in accordance with the settings of said first registers, a selective switch, means dependent upon the settings of said second registers for positioning the selective switch, and means controlled in accordance with the position taken by the selective switch for operating said second automatic switch to further extend said connection.

32. In a telephone system, an automatic switch, a group of registers, means for variably setting said registers, a second automatic switch, means controlled by said registers for operating said first automatic switch to extend a connection to the second automatic switch, a second group of registers, means for transmitting impulses over the extended connection to position the registers of said second group in accordance with the settings of said first registers, a variably operable selective switch, means

dependent upon the settings of said second registers for positioning said selective switch, and means controlled in accordance with the position taken by the selective switch for operating said second automatic switch to further extend said connection.

33. In a telephone system, an automatic switch, a group of registers, means for variably setting said registers, a second automatic switch, means controlled by said first registers for operating said first automatic switch to extend a connection to said second automatic switch, a second group of registers, means for setting the registers of said second group in accordance with the settings of said first registers, a third group of registers, means for setting the registers of said third group in accordance with the settings of the registers of said second group, and means controlled in accordance with the settings of said third group of registers for operating said second automatic switch to further extend said connection.

34. In a telephone system, automatic switches for extending connections, a group of registers, means for variably setting said registers, a second group of registers, means for setting the registers of said second group in accordance with the settings of said first registers, a plurality of selective switches, means dependent upon the settings of said second registers for selecting and positioning one of said selective switches, and means controlled in accordance with the position taken by said selective switch for operating said automatic switches.

35. In a telephone system, a group of variably operable registers, means for setting said registers, automatic switches, a second group of variably operable registers, means for setting the registers of said second group in positions corresponding to the settings of the registers of said first group, a plurality of selective switches, means dependent upon the settings of said second registers for selecting and positioning one of the selective switches, a third group of variably operable registers, means dependent upon the position taken by the selective switch for setting the registers of said third group, and means controlled in accordance with the settings of said last-mentioned registers for operating said automatic switches.

36. In a telephone system, a calling office, an automatic switch therein, a group of variably operable registers therein, means for setting said registers, a tandem office, an automatic switch therein, a group of registers in said tandem office, means controlled by said first registers for operating the automatic switch in the calling office to extend a connection to the automatic switch in said tandem office, means for variably setting the

- registers in the tandem office in accordance with the settings of said first registers, a third group of registers located in the tandem office, means for setting the registers 5 of said third group in accordance with the setting of the registers of said second-mentioned group, a called office having automatic switches therein, means controlled by said third group of registers for operating 10 the automatic switch at the tandem office to extend said connection to the automatic switches in said called office, and means for operating the automatic switches in said called office to further extend the connection.
- 15 37. In a telephone system, an automatic switch for extending telephone connections, a variably operable register, a circuit, means for transmitting impulses over said circuit to cause the setting of said register, a variably operable selective switch, means controlled by said register for positioning said selective switch, a controlling mechanism, means rendered effective by said selective switch in accordance with its setting for 20 determining the operation of said mechanism, and means controlled by said mechanism for selectively operating said automatic switch.
- 30 38. In a telephone system, automatic switches for extending telephone connections, a plurality of variably operable registers, an impulse circuit, means for sending impulses over said circuit representing wanted designations for causing the setting 35 of said registers, a variably operable selector switch, means controlled jointly by said registers for positioning said selective switch, a controlling mechanism, means ren-
- dered effective by said selective switch for determining the operation of said mechanism in accordance with the position of said switch, and means controlled by said mechanism for selectively operating said automatic switches. 40
39. In a telephone system, an automatic switch having a panel bank of passive terminals and active terminals for cooperating therewith, a sender mechanism, a second sender mechanism, means for setting said first mechanism to establish the registration 45 of a wanted designation thereon, means under control of said first sender mechanism for setting said second mechanism in accordance with the established registration, and means controlled by said second sender 50 mechanism for operating said automatic switch to establish a telephone connection. 55
40. In a telephone system, an automatic switch having a panel bank of terminals and movable terminals for cooperating therewith, a constantly moving member for driving said movable terminals, a sender mechanism, a second sender mechanism, means for variably setting said first mechanism to establish the registration of a 60 wanted designation thereon, means for transferring the established registration from the first sender to said second sender, and means under the control of said second sender for rendering said constantly moving 65 member effective to actuate said switch. 70

In witness whereof, I hereunto subscribe my name this 18th day of October, A. D. 1920.

EDMUND WATT HANCOCK.
